UNITED STATES PATENT OFFICE

2,333,485

TELEPHONE SYSTEM

Imre Molnar, Chicago, Ill., assignor to Automatic
Electric Laboratories, Inc., a corporation of
Delaware

Application October 19, 1942, Serial No. 462,519

10 Claims. (Cl. 179—27)

The present invention relates to telephone systems and more particularly to automatic tandem switching systems utilizing operator switchboard equipment of the character of that disclosed in the U. S. patents of Thomas F. Crocker, No. 2,167,710, granted August 1, 1939, and No. 2,230,053, granted January 28, 1941.

A telephone system of the automatic tandem switching type conventionally comprises two principal exchanges interconnected by toll lines; each exchange including an automatic toll switch train, operator switchboard equipment and outgoing trunks extending to suboffices. In handling toll traffic in the system the operator at the switchboard in one exchange first routes a connection therefrom via the associated toll switch train and an idle toll line to the toll switch train in the other exchange; the last-mentioned toll switch train is then selectively controlled to extend the connection to the operator switchboard in the other exchange, or to complete the connection to a subscriber substation in the other exchange independently of the operator switchboard therein, or to extend the connection over a trunk to the associated suboffice independently of the operator switchboard in the other exchange.

It is an object of the present invention to provide in a telephone system of the type noted an improved toll line circuit disposed in one exchange and responsive to a stop send signal transmitted over the associated toll line from the toll switch train in the other exchange for arresting operation of the register sender associated with the operator switchboard in the one exchange and then for initiating reoperation of the last-mentioned register sender a timed interval thereafter, whereby the register sender mentioned may resume the transmission of the switch directing signals over the toll line to the toll switch train in the other exchange.

Another object of the invention is to provide in a telephone system a trunk circuit interconnecting two operator switchboards, which trunk circuit embodies an improved arrangement for controlling supervision between the two switchboards incident to a rering operation performed at one of the switchboards.

A further object of the invention is to provide in a telephone system a line selecting switch which embodies an improved arrangement for performing both timed ring and timed rering operations over any line accessible to the line selecting mechanism incorporated in the switch which has been selected thereby.

Further features of the invention pertain to the particular arrangement of the circuit elements of the system, whereby the above-outlined and additional operating features are attained.

5 The invention, both as to its organization and method of operation, together with further objects and advantages thereof, will best be understood by reference to the following specification taken in connection with the accompanying drawings, in which Figure 1 illustrates the general arrangement of a telephone system embodying the present invention; Figs. 2 to 13, inclusive, taken together, illustrate the details of a system having incorporated therein the features of the invention, as briefly outlined above; and Fig. 14 10 illustrates the mode of combining Figs. 2 to 13, inclusive, to form a unified system.

20 *Description of the apparatus incorporated in the system*

Referring now more particularly to Fig. 1 of the drawings, the telephone system there illustrated comprises a remote exchange 20, a tandem exchange 30 and a distant exchange 40, the tandem exchange 30 constituting a toll switching center for the system. Each of the exchanges mentioned is of the automatic type each serving a number of local subscriber substations, the tandem exchange 30 serving a number of local 25 subscriber substations including the subscriber substation indicated at A. The remote exchange 20 and the tandem exchange 30 are interconnected by a number of toll lines, including the toll line 201; and the tandem exchange 30 and the distant exchange 40 are interconnected by a number of trunk lines, including the trunk line 1065. The remote exchange 20 comprises automatic switching and toll switchboard equipment of any suitable type indicated at 220; and the distant exchange 40 comprises automatic switching 30 equipment of any suitable type, not shown.

One end of the toll line 201 terminates in the equipment 220 provided in the remote exchange 20 and the other end of the toll line 201 terminates in a toll line circuit 200 provided in the tandem exchange 30. The toll line circuit 200 is provided with an incoming trunk 560 and also with an outgoing trunk 570, the outgoing trunk 570 terminating in a toll first selector 600 individual thereto provided in the tandem exchange 30. One end of the trunk line 1065 terminates in the equipment, not shown, provided in the distant exchange 40; while the other end of the trunk line 1065 terminates in a trunk circuit 1110 45 50 55 of any suitable type provided in the tandem ex-

change 30, the trunk circuit 1110 being provided with an incoming trunk 1060. Also the tandem exchange 30 comprises a number of toll second selectors, including the toll second selector 800, and a number of toll connectors, including the toll connector 1380. The toll second selector 800 is provided with an incoming trunk 810 accessible to the toll first selectors 600 etc., and has access to the incoming trunks 1060 etc. extending to the respective trunk circuits 1110 etc. The toll connector 1380 is of any suitable type and is provided with an incoming trunk 1390 accessible to the toll first selectors 600 etc., and has access to certain of the subscriber lines, including the subscriber line 1381 extending to the subscriber substation A. Also it is noted that the subscriber line 1381 extending to the subscriber substation A is provided with a line circuit 1382, of any suitable type, individual thereto. Further the tandem exchange 30 comprises a number of inward trunk circuits including the inward trunk circuit 1100. The inward trunk circuit 1100 is provided with an incoming trunk 1070 accessible to the toll second selectors 800 etc., and an outgoing trunk 1170.

Further the tandem exchange 30 is provided with toll switchboard equipment of the character of that disclosed in the Crocker patents mentioned, this equipment comprising a number of operator positions including the first operator position 1201. The first operator position 1201 is provided with a group of switching links individual thereto which are adapted to be selectively connected to an associated cable 1270 extending to the first operator position 1201. The group of switching links individual to the first operator position 1201 comprises the switching link illustrated which includes a link finder switch 1200 and a toll selector switch 1300. The link finder switch 1200 has access to the outgoing trunks 1170 etc. extending from the inward trunk circuits 1100 etc.; while the toll selector switch 1300 has access to the outgoing trunks 560 etc. extending to the toll line circuits 200 etc. and also to the incoming trunks 1390 etc. extending to the toll connectors 1380 etc. In the tandem exchange 30 the groups of switching links provided at the various operator positions at the switchboard, together with the toll first selectors 600 etc., the toll second selectors 800 etc. and the toll connectors 1380 etc., constitute a toll switch train. Also the tandem exchange 30 comprises a local switch train, not shown, which is utilized for the purpose of setting up local calls between the various subscriber substations A etc. therein. Also the toll switchboard equipment comprises a common start and level distributor 1101 associated with the various inward trunk circuits 1100 etc. and a position distributor 1105 which is associated with the common start and level distributor 1101 and utilized for the purpose of assigning idle ones of the operator positions at the switchboard in a predetermined order. Individually associated with the first operator position 1201 are a sending key set DK and a sender link SL-1. The sender link SL-1 comprises a switch LF-1 having access to a cable 1280 extending to the first operator position 1201 and to a number of cables 1286 etc. extending to the various switching links individually associated with the first operator position 1201, the cable 1286 being individual to the switching link illustrated. Also the sender link SL-1 comprises a switch SS-1 having access to a number of digit register and

control circuits 1390 etc. which are common to the operator positions at the switchboard.

Preferably, each of the toll line circuits is identical to the toll line circuit 200 which comprises, as best shown in Figs. 2 to 5, inclusive, a repeating coil 202 terminating one end of the toll line 201, a repeating coil 300 terminating the trunks 560 and 570, and a voice current repeater 205 and a pad 206 interposed between the repeating coils 202 and 300, the voice current repeater 205 and the pad 206 being of any suitable types. Also the toll line circuit 200 comprises a relay group, including a signal relay R210, a switch relay R320, a digit relay R330, a shunt relay R340, a pad relay R350, a seizure relay R360, two rering relays R370 and R410, an identity relay R420, a cutoff relay R430, a line relay R440, four control relays R450, R460, R470 and R510, an order relay R520, a seizure relay R530, a busy relay R540 and a supervisory relay R550. Further the toll line circuit 200 comprises a retard coil 213, an order lamp L502, an order key K503; and a control network connected and arranged in a manner more fully described hereinafter.

Preferably, each of the toll first selectors is identical to the toll first selector 600 which comprises, as best shown in Figs. 6 and 7, a switch mechanism 700 of the Strowger type, including a wiper set provided with four wipers 701 to 704, inclusive, mounted for both vertical and rotary movements, and an associated semi-cylindrical contact bank provided with ten vertically spaced-apart levers of contact sets arranged in circumferentially spaced-apart relation. Also the switch mechanism 700 comprises a vertical magnet M705 for driving the wiper set step by step in the vertical direction away from its normal vertical position, a rotary magnet M620 for driving the wiper set step by step in the rotary direction away from its normal rotary position, and a release magnet M706 for releasing the wiper set and for causing it to be returned to its normal rotary and vertical positions. Associated with the switch mechanism 700 are three sets of switch springs S615, S616 and S617 which are actuated when the wiper set is moved in the vertical direction away from its normal vertical position, a set of switch springs S618 which is actuated when the wiper set is moved in the vertical direction away from its normal vertical position adjacent certain specified levels, and three sets of switch springs S619, S707 and S710 which are actuated when the wiper set is driven in the rotary direction eleven steps away from its normal rotary position. Further the toll first selector 600 comprises a repeating coil 601; a relay group, including a switch-through relay R630, a line relay R640, a hold relay R650, a transfer relay R660, a control relay R670, two supervisory relays R720 and R730, an answer relay R740, a trunk test relay R750 and a cut-through relay R760; and a control network connected and arranged in a manner more fully described hereinafter.

Preferably, each of the toll second selectors is identical to the toll second selector 800 which comprises, as best shown in Figs. 8 to 10, inclusive, a switch mechanism 1010 of the Strowger type, including a wiper set provided with five wipers 1011 to 1015, inclusive, mounted for both vertical and rotary movements, and an associated semi-cylindrical contact bank provided with ten vertically spaced-apart levels of contact sets arranged in circumferentially spaced-apart rela-

tion. Also the switch mechanism 1010 comprises a vertical magnet M1031 for driving the wiper set step by step in the vertical direction away from its normal vertical position, a rotary magnet M906 for driving the wiper set step by step in the rotary direction away from its normal rotary position, and a release magnet M816 for releasing the wiper set and for causing it to be returned to its normal rotary and vertical positions. Associated with the switch mechanism 1010 are two sets of switch springs S817 and S820 which are actuated when the wiper set is moved in the vertical direction away from its normal vertical position, two sets of switch springs S821 and S911 which are actuated when the wiper set is moved in the vertical direction away from its normal vertical position adjacent certain specified levels and a set of switch springs S908 which is actuated when the wiper set is driven in the rotary direction away from its normal rotary position. Further the toll second selector 800 comprises a repeating coil 830; a relay group, including a switch-through relay R850, a line relay R860, a hold relay R870, two transfer relays R880 and R920, four control relays R930, R940, R950 and R1020, a hunt relay R960, a trunk test relay R1030 and a cut-through relay R1040; and a control network connected and arranged in a manner more fully described hereinafter.

Preferably, each of the inward trunk circuits is identical to the inward trunk circuit 1100 which comprises, as best shown in Fig. 11, a relay group, including a cutoff relay R1120, a control relay R1130, a seizure relay R1140, a ring relay R1150 and a supervisory relay R1160; and a control network connected and arranged in a manner more fully described hereinafter.

Preferably, the common start and level distributor circuit 1101, indicated in Fig. 11, is identical to the corresponding circuit shown in Figs. 6 and 10 of the later Crocker patent; while the position distributor 1105, indicated in Fig. 11, is identical to the corresponding distributor shown in Fig. 10 of the later Crocker patent. Also the equipment provided at the first operator position 1201, indicated in Fig. 12, is identical to the corresponding equipment shown in Figs. 11 to 14, inclusive, of the later Crocker patent; the link finder switch 1203, indicated in Fig. 12, is identical to the corresponding switch shown in Fig. 7 of the later Crocker patent; while the toll selector switch 1300, indicated in Fig. 13, is identical to the corresponding switch shown in Fig. 8 of the later Crocker patent.

Preferably, the sending key set DK, indicated in Fig. 13, is identical to the corresponding key set shown in Fig. 16 of the earlier Crocker patent; while the digit register and control circuit 1390, indicated in Fig. 13, is identical to the corresponding circuit shown in Figs. 17 to 21, inclusive, of the earlier Crocker patent. Finally, the sender link SL-1, indicated in Fig. 13, is substantially identical to the corresponding link shown in Figs. 15 and 16 of the earlier Crocker patent. More particularly, the sender link SL-1 is slightly different from the corresponding sender link mentioned in that it comprises the additional control relays R1360 and R1370 which are utilized for a purpose more fully explained hereinafter.

In the link finder switch 1203, the toll selector switch 1300, the first operator position 1201, the sender link SL-1 and the digit register and control circuit 1390, the portions of the equipment illustrated in Figs. 12 and 13 are provided with reference characters similar to the reference

characters provided in conjunction with the corresponding portions of the equipment disclosed in the Crocker patents mentioned; the reference characters mentioned differing only in the first two numerals and being identical in regard to the last two numerals.

A better understanding of the connection and arrangement of the telephone system will be facilitated from a consideration of the detailed operation of the various pieces of apparatus incorporated therein incident to the extension of the various calls between the exchanges illustrated, as will appear hereinafter.

Call from the remote exchange to the tandem exchange

Considering now the extension of a call from the remote exchange 20 to the tandem exchange 30, the operator at the switch-board in the remote

exchange 20 controls the associated equipment 220 in order to cause the automatic switching apparatus therein to seize an idle one of the toll lines, such, for example, as the toll line 201, extending to the tandem exchange 30. When the toll line 201 is thus seized, battery potential in the remote exchange 20 is applied to the line conductors thereof and, accordingly, by way of the winding 203 of the repeating coil 202 to the simplex conductor C214. The application of battery potential to the simplex conductor C214 completes an obvious circuit for energizing the intermediate and lower windings of the signal relay R210 in series and also a circuit for energizing the intermediate winding of the signal relay R210 in series with the retard coil 213, in view of the fact that ground potential in the toll line circuit 200 is applied at this time by way of the contacts 443, 434 and 552 to the control conductor C215. In view of the fact that the upper winding of the signal relay R210 is normally energized, polarizing this relay, the signal relay R210 is operated. Upon operating, the signal relay R210 completes, at the contacts 211, an obvious path for applying ground potential to the control conductor C212, thereby to complete a series circuit for energizing the windings of the seizure relay R530 and the pad relay R350 in the toll line circuit 200 and the line relay R640 in the toll first selector 600. The above-mentioned circuit extends from the grounded control conductor C212 by way of the contacts 461 and the winding of R530 to the resistors 305 and 307; from the resistor 307 by way of the winding of R350 and the contacts 325 to the winding 302 of the repeating coil 300 and from the resistor 307 by way of the contacts 327 to the winding 304 of the repeating coil 300; from the resistor 306 by way of the contacts 325 to the winding 302 of the repeating coil 300; from the windings 302 and 304 of the repeating coil 300 by way of the contacts 321 and 323, the line conductors C571 and C572 of the trunk 510, the contacts 631 and 634 and the windings 602 and 604 of the repeating coil 600 to the resistors 608 and 607; from the resistor 608 to the resistor 610; from the resistor 607 by way of the resistor 609 to the resistor 610; and from the resistor 610 by way of the winding of R640 to battery. At this point it is noted that the resistor 609 is included in the above-traced multiple branch in the circuit extending from the resistor 610 to the winding of the seizure relay R530 so that the winding of the pad relay R350 is energized, as previously noted. When this series circuit is thus completed the seizure relay R530 and the pad relay R350 in

the toll line circuit 200 and the line relay R640 in the toll first selector 600 operate.

Upon operating, the pad relay R350 completes, at the contacts 351, an obvious path for applying battery potential by way of the resistor 308 to the pad conductor C207 extending to the pad 206 for pad control purposes. Upon operating, the seizure relay R530 completes, at the contacts 531, an obvious circuit for energizing the winding of the busy relay R540, thereby to cause the latter relay to operate. Upon operating, the busy relay R540 completes, at the contacts 545, an obvious path for applying ground potential to the control conductor C563 of the trunk 560, thereby to mark the trunk 560 as busy to the various toll selector switches 1300 etc. having access thereto; and completes, at the contacts 541, an obvious path for applying ground potential to the control conductor C573 of the trunk 570 extending to the toll first selector 600. Also the busy relay R540 completes, at the contacts 543, an obvious circuit for energizing the lower winding of the supervisory relay R550 and completes, at the contacts 542, a circuit traced hereinafter for energizing the upper winding of the supervisory relay R550. When both the upper and lower windings of the supervisory relay R550 are thus energized this relay does not operate as it is of the differential type.

In the toll first selector 600, upon operating, the line relay R640 completes, at the contacts 641, an obvious circuit, including the contacts 637, for energizing the winding of the hold relay R650, thereby to cause the latter relay to operate. Upon operating, the hold relay R650 completes, at the contacts 651, a multiple path for applying ground potential to the hold conductor C573 of the trunk 570. The previously mentioned circuit for energizing the upper winding of the supervisory relay R550 in the toll line circuit 200 extends from the grounded control conductor C573 of the trunk 570 by way of the contacts 723, the contacts 708 of the set of switch springs S707, the contacts 639, the control conductor C574 of the trunk 570, the contacts 542 and the upper winding of R550 to battery. Also the application of ground potential to the control conductor C573 of the trunk 570 completes an obvious circuit, including the set of switch springs S617, for energizing the lower winding of the answer relay R740, thereby to cause the latter relay to operate shortly thereafter, the answer relay R740 being of the combination slow-to-operate and slow-to-release type. Upon operating, the answer relay R740 completes, at the contacts 741, an obvious circuit, including the contacts 651, for energizing the winding of the control relay R670, thereby to cause the latter relay to operate. Upon operating, the control relay R670 completes, at the contacts 673, a multiple holding circuit, including the contacts 651 and 763, for energizing the lower winding of the answer relay R740. At this time the toll first selector 600 is prepared to be operated in response to a digit repeated thereto by the toll line circuit 200, in a manner more fully explained hereinafter.

The operator at the switchboard in the remote exchange 20 then controls the associated equipment in order to cause the first digit to be transmitted over the toll line 201, battery potential being removed intermittently from the line conductors thereof and consequently from the simplex conductor C214, whereby the signal relay R210 follows the impulses of the digit mentioned. Each time the signal relay R210 restores and

reoperates it interrupts and then recompletes the previously mentioned path for applying ground potential to the control conductor C212, whereby the series circuit for energizing the windings of

5 the seizure relay R530 and the pad relay R350 in the toll line circuit 200 and the line relay R640 in the toll first selector 600 is controlled in order to cause the relays mentioned to follow the impulses of the first digit. The intermittent operation of the pad relay R350 and the seizure relay R530 in the toll line circuit 200 is without effect; while the intermittent operation of the line relay R640 in the toll first selector 600 effects operation thereof, in a manner more fully described hereinafter.

The operator at the switchboard in the remote exchange 20 controls the associated equipment, whereby several digits are transmitted over the toll line 201 and repeated by the toll line circuit 200 over the trunk 570 by the signal relay R210, in the manner described above; the first digit repeated over the trunk 570 operates the toll first selector 600, as previously noted, and the subsequent digit or digits repeated over the trunk 570 operate the succeeding elements of the toll switch train, in a manner more fully explained hereinafter. After the connection has been extended via the toll switch train and when the call is answered, the toll first selector 600 operates in order to cause ground potential to be removed from the control conductor C574 of the trunk 570, thereby to interrupt the previously traced circuit for energizing the upper winding of the supervisory relay R550, whereupon the latter relay operates. Upon operating, the supervisory relay R550 interrupts, at the contacts 552, the previously traced path for applying ground potential to the control conductor C215; and completes, at the contacts 551, an obvious path, including the resistor 310, for applying battery potential thereto. The application of battery potential to the control conductor C215 completes an obvious alternative circuit, including the retard coil 213, for energizing the lower winding 45 of the signal relay R210 and an obvious path, including the retard coil 213, for short-circuiting the intermediate winding of the signal relay R210, whereby battery potential is applied to the simplex conductor C214. When both the upper 50 and the lower windings of the signal relay R210 are thus energized the latter relay remains in its operated position; however, the application of battery potential to the simplex conductor C214 and consequently to the line conductors 55 of the toll line 201 operates the equipment 220 to render answer supervision to the operator at the toll switchboard in the remote exchange 20. At this time a connection is established from the toll switchboard in the remote exchange 20 via 60 the toll line 201, the toll line circuit 200, the trunk 570, the toll first selector 600 and the succeeding elements of the toll switch train to the called destination.

Considering now the release of the established connection from the remote exchange 20 to the tandem exchange 30, in the event the release is first initiated at the called destination, the toll first selector 600 is controlled in order to cause ground potential to be reapplied to the control conductor C574 of the trunk 570, thereby to recomplete the previously traced circuit for energizing the upper winding of the supervisory relay R550 in order to cause the latter relay to restore. Upon restoring, the supervisory relay R550 interrupts, at the contacts 551, the previously traced

path for applying battery potential to the control conductor C215, and completes, at the contacts 552, the previously traced path for applying ground potential to the control conductor C215. When battery potential is removed from the control conductor C215 the previously traced path for short-circuiting the intermediate winding of the signal relay R210 is interrupted; and when ground potential is reapplied to the control conductor C215 the previously traced circuits for energizing the intermediate and lower windings of the signal relay R210 are recompleted, whereby the signal relay R210 remains in its operated position. However, the removal of battery potential from and the reapplication of ground potential to the control conductor C215 cause battery potential to be removed from and ground potential to be reapplied to the simplex conductor C214 and consequently to the line conductors of the toll line 201, whereby the equipment 220 is operated to render release supervision to the operator at the toll switchboard in the remote exchange 20.

The operator at the toll switchboard in the remote exchange 20 controls the associated equipment 220, whereby the automatic switching equipment releases the toll line 201 removing battery potential from the line conductors thereof and rendering idle the toll line 201. The removal of battery potential in the equipment 220 in the remote exchange 20 from the toll line 201 and consequently from the simplex conductor C214 interrupts the previously traced circuits for energizing the intermediate and lower windings of the signal relay R210, whereupon the latter relay restores. Upon restoring, the signal relay R210 interrupts, at the contacts 211, the previously mentioned path for applying ground potential to the control conductor C212, thereby to interrupt the previously traced series circuit for energizing the windings of the seizure relay R530 and the pad relay R350 in the toll line circuit 200 and the line relay R640 in the toll first selector 600 in the event the latter relay occupies its operated position at this time, whereupon the relays mentioned restore. Upon restoring, the pad relay R350 interrupts, at the contacts 351, the application of battery potential to the pad conductor C207, whereby the pad 206 is controlled. Upon restoring, the seizure relay R530 interrupts, at the contacts 531, the previously mentioned circuit for energizing the winding of the busy relay R540, thereby to cause the latter relay to restore shortly thereafter, the busy relay R540 being of the slow-to-release type. Upon restoring, the busy relay R540 interrupts, at the contacts 545, the previously mentioned path for applying ground potential to the control conductor C563 of the trunk 560, and completes, at the contacts 544, an obvious path, including the contacts 521, for applying battery potential by way of the winding of the seizure relay R360 to the control conductor C563 of the trunk 560, thereby to mark the trunk 560 as idle to the toll selector switches 1300 etc. Also the busy relay R540 interrupts, at the contacts 541, the previously mentioned path for applying ground potential to the control conductor C573 of the trunk 570 extending to the toll first selector 608. When ground potential is removed from the control conductor C573 of the trunk 570 and the line relay R640 in the toll first selector 600 is restored, the toll first selector 600 and the succeeding toll switch train are released, in a manner more fully explained hereinafter. Finally the busy relay R540 interrupts, at the contacts

542 and 543, the previously mentioned circuits for energizing the upper and lower windings of the supervisory relay R550, whereby the latter relay is retained in its restored position. At this time the established connection between the toll switchboard in the remote exchange 20 and the toll line circuit 200 in the tandem exchange 30 is completely released; the toll first selector 600 and the succeeding toll switch train are completely released and the toll line circuit 200 is completely released and available for access either via the toll line 201 or the trunk 560.

Operation of the toll first selector 600

15 As previously explained, when the toll line 201 is seized by the automatic switching equipment 220 in the remote exchange 20 the toll line circuit 200 operates in order to effect the seizure of the toll first selector 600, whereby the line relay R640, the hold relay R650, the answer relay R740 and the control relay R670 are operated, all in the manner previously explained. Also, as previously noted, the first digit transmitted over the toll line 201 is repeated by the signal relay R210 in the toll line circuit 200 to the line relay R640, whereby the latter relay follows the digit mentioned. Considering now the operation of the toll first selector 600 in response to the control of the line relay R640 in accordance with the first digit, each time the line relay R640 restores and reoperates it interrupts and then recompletes, at the contacts 641, the previously traced circuit for energizing the winding of the hold relay R560; however, the latter relay remains in its operated position during impulsing as it is of the slow-to-release type. Also each time the line relay R640 restores and reoperates it completes and then interrupts, at the contacts 642, a multiple circuit, including the contacts 637, 653 and 675, for energizing the winding of the transfer relay R660 and for energizing the vertical magnet M705, whereby the transfer relay R660 is operated and remains operated during impulsing as it is of the slow-to-release type and the vertical magnet M705 operates and restores in order to drive the wiper set of the switch mechanism 700 one step in the vertical direction.

Upon operating, the transfer relay R660 completes, at the contacts 661, an obvious path for short-circuiting the winding 603 of the repeating coil 601, for a purpose more fully explained hereinafter. When the wiper set is driven one step in the vertical direction away from its normal vertical position the sets of switch springs S615, S616 and S617 are actuated. More particularly, the set of switch springs S617 is actuated into disengagement, thereby to interrupt the previously traced operating circuit for energizing the lower winding of the answer relay R740; however, the latter relay is retained in its operated position at this time due to the completed holding circuit for energizing the lower winding thereof. Accordingly, at this time, the vertical magnet M705 is operated a number of times corresponding to the number of impulses in the first digit, whereby the wiper set is driven in the vertical direction away from its normal vertical position a corresponding number of steps adjacent the corresponding level in the associated contact bank. At the conclusion of the first digit the line relay R640 is retained in its operated position in order to retain operated the hold relay R650; and shortly thereafter the transfer relay R660 restores, the circuit for energizing the winding

of the transfer relay R660 being interrupted, at the contacts 642, by the operated line relay R640 at this time. Upon restoring, the transfer relay R660 interrupts, at the contacts 661, the previously mentioned path for short-circuiting the winding 603 of the repeating coil 601; and completes, at the contacts 662, a circuit, including the contacts 651, 751, 765, the set of switch springs S615 and the contacts 621, for energizing the rotary magnet M620. When thus energized the rotary magnet M620 operates, thereby to drive the wiper set one step in the rotary direction away from its normal rotary position and to interrupt, at the contacts 621, the above-traced circuit for energizing the rotary magnet M620. The rotary magnet M620 then restores, thereby to re-complete, at the contacts 621, the previously traced circuit for energizing the rotary magnet M620. Accordingly, the rotary magnet M620 operates intermittently, thereby to drive the wiper set step by step in the rotary direction away from its normal rotary position, whereby the trunks in the associated level are successively tested.

More particularly, when the wiper set engages a contact set in the associated level terminating a busy trunk, ground potential on the control conductor thereof is applied to the control wiper 703, thereby to complete an obvious path, including the contacts 652, for short-circuiting the winding of the trunk test relay R750. On the other hand, when the wiper set engages a contact set in the associated level terminating an idle trunk, battery potential on the control conductor thereof is applied to the control wiper 703, thereby to complete an obvious circuit, including the contacts 652, for energizing the winding of the trunk test relay R750. When thus energized the trunk test relay R750 operates to interrupt, at the contacts 751, a point in the previously traced circuit for energizing the rotary magnet M620, thereby positively to prevent further operation of the latter magnet and to arrest further movement in the rotary direction of the wiper set. Also the trunk test relay R750 completes, at the contacts 752, an obvious circuit, including the contacts 651, for energizing the upper winding of the cut-through relay R760, thereby to cause the latter relay to operate. Upon operating, the cut-through relay R760 completes, at the contacts 764, an obvious holding circuit, including the contacts 651, for energizing the upper winding thereof; and completes, at the contacts 761 and 762, connections to the line wipers 701 and 702 of the wiper set. Also the cut-through relay R760 completes, at the contacts 766, an obvious path for applying ground potential to the control wiper 703 and an obvious multiple path for short-circuiting the winding of the trunk test relay R750 in order to cause the latter relay to restore. Further the cut-through relay R760 completes, at the contacts 769, an obvious path, including the contacts 630 and 742, for applying ground potential to the control wiper 704 of the wiper set; and interrupts, at the contacts 763, the previously traced holding circuit for energizing the lower winding of the answer relay R740. The answer relay R740 is retained in its operated position at this time due to the completion of the loop circuit for energizing the upper winding thereof, this circuit extending from the line wiper 701 by way of the contacts 761, the contacts 633, the winding 603 of the repeating coil 601, the contacts 672 and 641, the upper winding of R740,

the winding 605 of the repeating coil 601 and the contacts 636 and 762 to the line wiper 702.

The above-described operation of the toll first selector 600 takes place when it is operated to select a trunk extending to an idle toll connector, such, for example, as the trunk 1390, extending to the toll connector 1380. Now assuming that the toll first selector 600 has operated in the manner described above and has selected the trunk 1390 extending to the toll connector 1380, the toll first selector 600 then receives two additional digits which are repeated thereby over the trunk 1390 to the toll connector 1380. More particularly, the line relay R640 follows the second digit in order to repeat, at the contacts 641', the impulses thereof over the previously traced loop circuit to the toll connector 1380. Also the intermittent operation of the line relay R640 during the second digit effects reoperation of the transfer relay R660, whereby the latter relay re-completes, at the contacts 661, the previously traced path for short-circuiting the winding 603 of the repeating coil 601 in order to improve impulsing over the loop circuit mentioned. It is noted that the answer relay R740 remains operated during impulsing as it is of the slow-to-release type. Further it is noted that each time the line relay R640 restores it completes, at the contacts 642, a circuit, including the contacts 637, 653, 675, 767 and 673, for energizing the lower winding of the answer relay R740, thereby positively to prevent restoration of the last-mentioned relay. At the conclusion of the second digit the line relay R640 remains operated, whereupon the transfer relay R660 restores shortly thereafter, in the manner previously explained, in order to interrupt, at the contacts 661, the previously mentioned path for short-circuiting the winding 603 of the repeating coil 601, whereby the previously traced loop circuit, including the upper winding of the answer relay R740 and the windings 603 and 605 of the repeating coil 601, is again recompleted. In a similar manner, the line relay R640 in the toll first selector 600 repeats the third digit over the trunk 1390 to the toll connector 1380.

The toll connector 1380 operates in response to the two digits repeated thereto by the toll first selector 600 in accordance with conventional practice in order to select the corresponding subscriber line extending to a called subscriber substation. For example, the toll connector 1380 may be operated to select the subscriber line 1381 extending to the called subscriber substation A. At this time the toll connector 1380 tests the idle or busy condition of the subscriber line 1381 extending to the called subscriber substation A.

In the event the subscriber line 1381 extending to the called subscriber substation A is tested as busy, the toll connector 1380 may operate to cause busy tone current to be returned over the previously traced loop circuit, including the windings 603 and 605 of the repeating coil 601, whereby a corresponding busy tone voltage is induced in the windings 602 and 604 thereof in order to cause busy tone current to be returned over the trunk 570 to the windings 302 and 304 of the repeating coil 300 in the toll line circuit 200. The busy tone current traversing the windings 302 and 304 of the repeating coil 300 causes busy tone current to be returned via the pad 206, the voice current repeater 205 and the repeating coil 202 over the toll line 201 to the operator position at the toll switchboard in the

remote exchange 20, in an obvious manner. Also the toll connector 1380 operates in order to interrupt the previously traced loop circuit for energizing the upper winding of the answer relay R740, whereby the latter relay restores shortly thereafter as it is of the combination slow-to-operate and slow-to-release type. Upon restoring, the answer relay R740 interrupts, at the contacts 741, the previously traced circuit for energizing the winding of the control relay R670, thereby to cause the latter relay to restore shortly thereafter, the control relay R670 being of the slow-to-release type.

Similarly, in the event the subscriber line 1381 extending to the called subscriber substation A is tested as busy, the toll connector 1380 may operate to cause ground potential to be applied intermittently to the negative line conductor of the trunk 1390 and consequently to the corresponding line wiper 701 of the switch mechanism 700. This intermittent application of ground potential completes a circuit, including the contacts 761 and 633, the winding 603 of the repeating coil 601 and the contacts 671, for energizing in series the upper winding of the supervisory relays R730 and R720. When this series circuit is completed the supervisory relay R730 operates to complete, at the contacts 732, an obvious holding circuit, including the contacts 651, for energizing the lower winding thereof. On the other hand, the upper winding of the supervisory relay R720 is energized intermittently in order to cause this relay to operate and restore. Each time the supervisory relay R720 operates and restores it interrupts and then recomplete, at the contacts 723, the previously traced path for applying ground potential to the control conductor C574 of the trunk 570, thereby to cause the supervisory relay R550 in the toll line circuit 200 to operate and restore intermittently in order to render busy supervision to the operator at the toll switchboard in the remote exchange 20, in the manner previously explained.

On the other hand, in the event the subscriber line 1381 extending to the called subscriber substation A is tested as idle, the toll connector 1380 switches through in order to interrupt the previously traced loop circuit for energizing the upper winding of the answer relay R740 in order to cause the latter relay to restore shortly thereafter and effect the subsequent restoration of the control relay R670, in the manner previously explained. Also the answer relay R740 interrupts, at the contacts 742, the previously traced path for applying ground potential to the control wiper 704 of the wiper set. Upon restoring, the control relay R670 recomplete, at the contacts 676, an alternative path, including the contacts 630 and 769, for reapplying ground potential to the control wiper 704 of the wiper set. Accordingly, ground potential is removed from and then reapplied, a short time interval later, to the control wiper 704. The removal of ground potential, during the time interval mentioned, from the control wiper 704, causes the toll connector 1380 to initiate a ringing operation, whereby ringing current is projected over the subscriber line 1381 to the called subscriber substation A.

When the subscriber at the called subscriber substation A answers the call a circuit is completed for energizing in series the upper and lower windings of the supervisory relay R720 and the upper winding of the supervisory relay R730, this circuit extending from ground by way

of the lower winding of R720, the contacts 674, the winding 603 of the repeating coil 601, the contacts 636 and 762 to the line wiper 702, and from battery by way of the upper windings of the supervisory relays R720 and R730, the contacts 671, the winding 603 of the repeating coil 601 and the contacts 633 and 671 to the line wiper 701; this loop circuit being extended by way of the trunk 1390, the toll connector 1380 and the subscriber line 1381 to the called subscriber substation A, whereat it is completed. When the supervisory relays R720 and R730 are thus energized they operate. Upon operating, the supervisory relay R720 completes, at the contacts 722, an obvious circuit, including the contacts 651, for energizing the lower winding of the supervisory relay R730, and interrupts, at the contacts 723, the previously traced path for applying ground potential to the control conductor C574 of the trunk 570 in order to interrupt the previously traced circuit for energizing the upper winding of the supervisory relay R550 in the toll line circuit 200, whereupon the latter relay restores in the manner previously explained. Also the supervisory relay R720 interrupts, at the contacts 721, a normally completed path, including the condenser 612 and the resistor 611, across the line conductors C571 and C572 of the trunk 570, thereby to improve the fidelity of the repeating coil 601. Upon operating, the supervisory relay R730 completes, at the contacts 732, an obvious alternative holding circuit, including the contacts 651, for energizing the lower winding thereof. Also the supervisory relay R730 completes, at the contacts 731, an obvious path for short-circuiting the upper winding thereof, thereby to reduce the resistance of the previously traced loop circuit extending between the toll first selector 600 and the toll connector 1380. At this time, transmission battery is applied by way of the upper and lower windings of the supervisory relay R720 in the toll first selector 600 via the trunk 1390, the toll connector 1380 and the subscriber line 1381 to the called subscriber substation A.

When the subscriber at the called subscriber substation A initiates the release of the established connection by replacing the receiver of the telephone instrument thereat upon its associated switchhook the previously traced loop circuit for energizing in series the upper and lower windings of the supervisory relay R720 is interrupted, thereby to cause the latter relay to restore. Upon restoring, the supervisory relay R720 recomplete, at the contacts 723, the previously traced path for applying ground potential to the control conductor C574 of the trunk 570, thereby to recomplete the previously traced circuit for energizing the upper winding of the supervisory relay R550 in the toll line circuit 200 in order to cause the latter relay to restore. Upon restoring, the supervisory relay R550 causes release supervision to be rendered to the operator at the toll switchboard in the remote exchange 20, in the manner previously explained.

The operator at the toll switchboard in the remote exchange 20 then effects the release of the automatic switching apparatus therein, whereby the toll line 201 and the toll line circuit 200 are released, in the manner previously explained, whereby the previously traced circuit for energizing the winding of the line relay R640 is interrupted in order to cause the latter relay to restore. Upon restoring, the line relay R640 interrupts, at the contacts 641, the previously men-

tioned circuit for energizing the winding of the hold relay R650, thereby to cause the latter relay to restore shortly thereafter, the hold relay R650 being of the slow-to-release type. Upon restoring, the hold relay R650 completes, at the contacts 654, an obvious circuit, including the contacts 637, 642 and 663 and the set of switch springs S616, for energizing the release magnet M706, whereupon the latter magnet operates in order to effect the release of the wiper set of the switch mechanism 700. When the wiper set is thus released it is returned to its normal rotary and vertical positions, whereupon the sets of switch springs S615, S616 and S617 are actuated. More particularly, the set of switch springs S616 is actuated into disengagement, thereby to interrupt the previously traced circuit for energizing the release magnet M706 in order to cause the latter magnet to restore. Also, upon restoring, the hold relay R650 interrupts, at the contacts 651, the previously mentioned path for applying ground potential to the control conductor C573 of the trunk 570, thereby to interrupt the previously traced holding circuit for energizing the lower winding of the supervisory relay R730 and the previously traced holding circuit for energizing the upper winding of the cut-through relay R760 in order to cause the relays mentioned to restore. Upon restoring, the cut-through relay R760 interrupts, at the contacts 766, the previously mentioned path for applying ground potential to the control wiper 703 of the wiper set, thereby to effect the release of the toll connector 1380. When the toll connector 1380 is thus released the line circuit 1382 is controlled in order to mark the subscriber line 1281 extending to the called subscriber substation A as idle to the toll connectors, as well as the local switch train, having access thereto. At this time the toll first selector 600 is completely released, together with the individually associated toll line circuit 200.

In the foregoing explanation of the mode of operation of the toll first selector 600 to select an idle trunk in the group extending to the toll connectors 1380 etc., the wiper set might have selected an idle trunk extending to an interceptor operator position, not shown. In this event, the trunk test relay R750 operates in order to effect operation of the cut-through relay R760, in the manner previously explained. In this case, upon operating, the switch-through relay R760 completes, at the contacts 761 and 762, the previously traced path for connecting the upper winding of the answer relay R740 across the line wipers 701 and 702 of the wiper set and consequently across the line conductors of the trunk extending to the interceptor operator position. The line conductors of the trunk extending to the interceptor operator position are dry of ground and battery potentials and comprise a high resistance connection between the line conductors thereof. Accordingly, the upper winding of the answer relay R740 is not energized and shortly thereafter the latter relay restores in order to effect the restoration of the control relay R670 after a further short time interval. Upon restoring, the control relay R670 completes, at the contacts 671 and 674, the previously traced series circuit for energizing the upper and lower windings of the supervisory relay R720 and the upper winding of the supervisory relay R730, the circuit mentioned including the line conductors of the trunk extending to the interceptor operator position and the high resistance bridge therebetween. When

this series circuit is completed the supervisory relay R720 does not operate as it is of the marginal type, whereas the supervisory relay R730 operates only to its first step position, closing the contacts 734, whereby the lower winding of the supervisory relay R730 is energized by way of an obvious circuit, including the contacts 733, the condenser 711 and the tone conductor C112 with interceptor tone current. The interceptor tone current traversing the lower winding of the supervisory relay R730 induces a corresponding interceptor tone voltage in the upper winding thereof which is connected by way of the condenser 713, the winding 605 of the repeating coil 601, and the contacts 636 and 762 to the line wiper 702 and by way of the contacts 671, the winding 603 of the repeating coil 601 and the contacts 633 and 761 to the line wiper 701, the line wipers engaging the line conductors of the trunk extending to the interceptor operator position. Accordingly, when the operator at the interceptor operator position answers the call the interceptor voltage appearing on the associated trunk warns her that the call intercepted is a toll call. The operator at the interceptor operator position may then operate a key thereat in order to reduce the resistance of the bridge between the line conductors of the trunk extending thereto, whereby the upper winding of the supervisory relay R730 and the upper and lower windings of the supervisory relay R720 are sufficiently energized in order to cause these relays to operate, in the manner previously explained. In this case, the operated connection is completed from the toll switchboard in the remote exchange 20 via the toll line 201, the toll line circuit 200, the toll first selector 600 and the interceptor trunk to the interceptor operator position in the tandem exchange 30. The release of this established connection is the same as that previously described in conjunction with the connection completed to the called subscriber station A.

In the above-described operation of the toll first selector 600, had the wiper set been operated to one of the specified levels, such, for example, as the level in which the trunk 810 extending to the toll second selector 800 terminates, the set of switch springs S618 would have been operated. In this event, operation of the rotary magnet M620 is initiated under the control of the trunk test relay R750, in the manner previously explained, whereby the wiper set is moved step by step in the rotary direction in order to test the successive trunks in the selected level. When an idle trunk in the selected level, such, for example, as the trunk 810, extending to the toll second selector 800 is tested, the trunk test relay R750 operates in order to effect operation of the cut-through relay R760, in the manner previously explained. Upon operating, the cut-through relay R760 interrupts, at the contacts 765, the previously traced circuit for energizing the rotary magnet M620, thereby positively to arrest further operation of the latter magnet and further movement of the wiper set in the rotary direction. At this point it is noted that the trunk 810 is marked as idle to the toll first selector 600 by the application of battery potential upon the control conductor C813 thereof. More particularly, battery potential in the toll second selector 800 is applied by way of the upper winding of the transfer relay R800, the contacts 819 of the set of switch springs S817, the contacts 909 of the set of switch springs S908 and the contacts 1045 and 1031 to the control conductor C813 of the trunk 810.

Also, in this case, upon operating, the trunk test relay R750 completes, at the contacts 752, an obvious circuit, including the contacts 651 and the sets of switch springs S619 and S618, for energizing the winding of the switch-through relay R630, thereby to cause the latter relay to operate. Also, upon operating, the cut-through relay R760 interrupts, at the contacts 763, the previously traced circuit for energizing the lower winding of the answer relay R740, and completes, at the contacts 766, the previously traced path for short-circuiting the winding of the trunk test relay R750. The trunk test relay R750 then restores and shortly thereafter the answer relay R740 restores, the latter relay being of the slow-to-release type, as previously noted.

Upon operating, the switch-through relay R630 interrupts, at the contacts 631 and 634, the previously traced circuit for energizing the winding of the line relay R640, thereby to cause the latter relay to restore. Also the switch-through relay R630 completes, at the contacts 632 and 635, a direct connection, including the contacts 761 and 762, between the line conductors of the trunk 570 and the line wipers 701 and 702 of the wiper set, whereby the grounded control conductor C212 in the toll line circuit 200 is connected through the windings of the seizure relay R530 and the pad relay R350 therein directly to the line conductors C811 and C812 of the trunk 810 and consequently through the winding of the line relay R860 in the toll second selector 800 to battery, in a manner more fully explained hereinafter. Also the switch-through relay R630 interrupts, at the contacts 633 and 636, the normally completed connections between the windings 603 and 605 of the repeating coil 601 and the line wipers 701 and 702 of the wiper set. Further the switch-through relay R630 interrupts, at the contacts 639, the previously traced path for applying ground potential in the toll first selector 600 to the control conductor C574 of the trunk 570, and completes, at the contacts 638, an obvious connection including the contacts 769 between the control conductor C574 of the trunk 570 and the control wiper 704 of the wiper set. At this time ground potential in the toll second selector 800 is applied by way of the contacts 1025 and 1044' to the control conductor C814 of the trunk 810 and consequently to the control wiper 704 of the wiper set, whereby ground potential is retained upon the control conductor C574 of the trunk 570 in order to retain energized the upper winding of the supervisory relay R550 in the toll line circuit 200.

Upon restoring, the line relay R640 effects the restoration of the hold relay R650 shortly thereafter; and, upon restoring, the answer relay R740 effects the restoration of the control relay R670 shortly thereafter. Upon restoring, the hold relay R650 interrupts, at the contacts 651, the multiple path for applying ground potential in the toll first selector 600 to the control conductor C573 of the trunk 570; however, ground potential in the toll line circuit 200 is retained upon the control conductor C573 of the trunk 570. Accordingly, the switch-through relay R630 and the cut-through relay R760 in the toll first selector 600 remain in their operated positions. At this time the toll line circuit 200 is connected directly through the toll first selector 600 to the toll second selector 800 and digits received in the toll line circuit 200 may be repeated therefrom directly through the toll first selector 600 to the toll

second selector 800 in order selectively to control the operation thereof, in a manner more fully explained hereinafter.

The release of the toll first selector 600, when it occupies its switch-through position as explained above, is effected when the toll line circuit 200 is released in order to cause ground potential to be removed from the control conductor C573 of the trunk 570. When ground potential is removed from the control conductor C573 of the trunk 570 the previously traced multiple circuits for energizing the winding of the switch-through relay R630 and the upper winding of the cut-through relay R760 are interrupted in order to cause these relays to restore. Upon restoring, the switch-through relay R630 completes, at the contacts 637, the previously traced circuit for energizing the release magnet M706, thereby to cause the latter magnet to operate and release the wiper set of the switch mechanism 700. The remainder of the release of the toll first selector 600 is the same as that previously explained.

In the foregoing explanation of the mode of operation of the toll first selector 600 to select an idle trunk in the previously selected level, it is pointed out that, should the wiper set of the switch mechanism 700 be driven across the entire level of contact sets eleven steps in the rotary direction without testing a trunk in the selected level as idle, the sets of switch springs S619, S707 and S710 are actuated. More particularly, in this case, the set of switch springs S707 is actuated, thereby to interrupt, at the contacts 708 thereof, the previously traced path for applying ground potential to the control conductor C574 of the trunk 570, and to complete, at the contacts 709 thereof, an obvious path, including the impulse conductor C613 and the contacts 639, for connecting 120 ground impulses per minute to the control conductor C574 of the trunk 570. This application of 120 ground impulses per minute to the control conductor C574 of the trunk 570 causes the supervisory relay R550 in the toll line circuit 200 to follow, in an obvious manner, in order to repeat the all-trunks-busy supervision to the operator at the toll switchboard in the remote exchange 20. Also the set of switch springs S710 is actuated into engagement, thereby to complete an obvious circuit, including the contacts 652, for energizing the winding of the trunk test relay R570 in series with the lower winding of the cut-through relay R760 in order to cause the trunk test relay R750 to operate. Upon operating, the trunk test relay R750 interrupts, at the contacts 751, the previously traced circuit for energizing the rotary magnet M620, and completes, at the contacts 752, the previously traced circuit for energizing the upper winding of the cut-through relay R760. At this time both the upper and lower windings of the cut-through relay R760 are energized, thereby positively to prevent operation of this relay, the cut-through relay R760 being of the differential type. The subsequent release of the toll first selector 600 is the same as that previously explained.

Operation of the toll second selector 800

As previously explained, when the toll first selector 600 seizes the trunk 810 extending to the toll second selector 800 and switches through, the ground potential appearing upon the control conductor C212 in the toll line circuit 200 is forwarded via the line wipers 701 and 702 of the wiper set of the switch mechanism 700 to the line conductors C811 and C812 of the trunk 810,

whereby the winding of the line relay R860 in the toll second selector 800 is energized. More particularly, battery potential in the toll second selector 800 is connected by way of the winding of the line relay R860 to the resistor 840 and therefrom by way of the resistor 838, the winding 831 of the repeating coil 830 and the contacts 851 to the line conductor C811, and from the resistor 840 by way of the resistors 839 and 837, the winding 833 of the repeating coil 830 and the contacts 854 to the line conductor C812. This circuit is further extended by way of the toll first selector 600 and the trunk 570 by way of the winding of the pad relay R350 and the winding of the seizure relay R530 in the toll line circuit 200 to the grounded control conductor C212, as previously traced. Also it is noted that one of the multiple branches in the above-traced circuit includes the resistor 839, whereby the winding of the pad relay R350 in the toll line circuit 200 is energized in order to retain the latter relay in its operated position, as previously explained. Accordingly, at this time, the line relay R860 in the toll second selector 800 is energized and operates to complete, at the contacts 861, an obvious circuit, including the contacts 851, for energizing the winding of the hold relay R870, thereby to cause the latter relay to operate. Further it is noted that, when the toll first selector 600 seizes the trunk 810, ground potential is applied to the control conductor C813 thereof, whereby the previously traced circuit for energizing the upper winding of the transfer relay R880 is completed in order to cause the latter relay to operate. Upon operating, the hold relay R870 completes, at the contacts 876, a circuit, including the set of switch springs S911, the contacts 1042' and 936, for energizing the upper winding of the control relay R930, and completes, at the contacts 876, a multiple circuit, including the set of switch springs S911, the contacts 1042', 937, 951 and 946, for energizing the lower winding of the control relay R930. When both the upper and lower windings of the control relay R930 are thus energized the latter relay does not operate as it is of the differential type. Also the hold relay R870 completes, at the contacts 876, a further multiple circuit, including the set of switch springs S911, the contacts 1042' and 951, for energizing the upper winding of the control relay R950. Shortly after the control relay R950 is thus energized it operates, as it is of the combination slow-to-operate and slow-to-release type, to complete, at the contacts 952 and 954, a holding circuit, including the contacts 942, the set of switch springs S911 and the contacts 876, for energizing the lower winding thereof. Also the control relay R950 interrupts, at the contacts 951, the previously traced circuit for energizing the upper winding thereof, and interrupts, at the contacts 957, the previously traced original circuit for energizing the lower winding of the control relay R930. Further the control relay R950 completes, at the contacts 956, an alternative circuit, including the contacts 946, 942 and 954, the set of switch springs S911 and the contacts 876, for energizing the lower winding of the control relay R930, thereby to maintain the latter relay in its restored position.

At this time the toll second selector 800 is in readiness to receive the second digit repeated from the toll line circuit 200, whereby the line relay R860 follows the impulses of the digit mentioned, in an obvious manner. Each time the line relay R860 restores and reoperates it in-

terrupts and then recompletes, at the contacts 861, the previously mentioned circuit for energizing the winding of the hold relay R870, thereby to retain the latter relay in its operated position during impulsing, the hold relay R870 being of the slow-to-release type. Also each time the line relay R860 restores and reoperates it completes and then interrupts, at the contacts 862, a circuit, including the contacts 857, 874 and 1049, for energizing the lower winding of the transfer relay R880 and a multiple circuit, including the contacts 925 and 1021, for energizing the vertical magnet M1001, whereby the transfer relay R880 is retained in its operated position and the vertical magnet M1001 operates and restores in order to drive the wiper set of the switch mechanism 1010 one step in the vertical direction away from its normal vertical position.

When the wiper set is driven one step in the vertical direction away from its normal vertical position the sets of switch springs S817 and S820 are actuated. More particularly, the set of switch springs S817 is actuated, thereby to interrupt, at the contacts 819 thereof, the previously traced circuit for energizing the upper winding of the transfer relay R880. Accordingly, at this time, the vertical magnet M1001 is operated a number of times corresponding to the number of impulses in the second digit, thereby to drive the wiper set a corresponding number of steps in the vertical direction away from its normal vertical position, whereby a corresponding level in the associated contact bank is selected by the wiper set. At the conclusion of the second digit the line relay R860 remains operated, thereby to retain operated the hold relay R870; and shortly thereafter the transfer relay R880 restores, the latter relay being of the slow-to-release type. Upon restoring, the transfer relay R880 completes, at the contacts 883, a circuit, including the grounded control conductor C813 of the trunk 810, the contacts 1031 and 1045, the contacts 909 of the set of switch springs S908, and the contacts 818 of the set of switch springs S817, for energizing the winding of the transfer relay R920, thereby to cause the latter relay to operate. Upon operating, the transfer relay R920 interrupts, at the contacts 925, a further point in the previously traced circuit for energizing the vertical magnet M1001 in multiple with the lower winding of the transfer relay R880, and prepares, at the contacts 923, a circuit traced hereinafter for energizing the lower winding of the transfer relay R880 in multiple with the rotary magnet M906. Also the transfer relay R920 completes, at the contacts 922, an alternative circuit, including the contacts 909 of the set of switch springs S908, the contacts 1045 and 1031 and the grounded control conductor C813, for energizing the upper winding of the transfer relay R880, thereby to cause the latter relay to reoperate. Upon reoperating, the transfer relay R880 interrupts, at the contacts 883, the previously traced original circuit for energizing the winding of the transfer relay R920, and completes, at the contacts 882, an alternative circuit, including the contacts 926, 1045 and 1031 and the grounded control conductor C813, for energizing the winding of the transfer relay R920 in series with the lower winding of the control relay R1020. When this series circuit is completed the control relay R1020 operates to complete, at the contacts 1022, an obvious holding circuit, including the contacts 871, for energizing the upper winding thereof, and to complete, at the contacts 1023, an obvious path for short-cir-

cuiting the lower winding thereof, whereby the winding of the transfer relay R920 is energized directly from ground potential in order to retain the latter relay in its operated position. Also the control relay R1020 interrupts, at the contacts 1025, a normally completed path, including the contacts 1044', for applying ground potential to the control conductor C814 of the trunk 810, and completes, at the contacts 1024, an alternative path, including the contacts 927 and 1044', for applying ground potential to the control conductor C814 of the trunk 810. The application of ground potential to the control conductor C814 of the trunk 810 is connected by the toll first selector 600 to the control conductor C574 of the trunk 570, thereby to retain energized the upper winding of the supervisory relay R550 in the toll line circuit 200.

The toll line circuit 200 then operates to repeat the third digit over the toll first selector 600 and the trunk 810 to the line relay R860, whereby the latter relay follows the impulses of the digit mentioned. At this time, upon restoring and reoperating, the line relay R860 completes and then interrupts, at the contacts 862, a circuit, including the contacts 857, 874 and 1049, for energizing the lower winding of the transfer relay R880, and a multiple circuit, including the contacts 923, for energizing the rotary magnet M906, whereby the transfer relay R880 is retained in its operated position during impulsion and the rotary magnet M906 is operated and restored in order to drive the wiper set one step in the rotary direction away from its normal rotary position. When the wiper set is driven one step in the rotary direction the set of switch springs S908 is actuated, thereby to interrupt, at the contacts 909 thereof, the previously traced alternative circuit for energizing the upper winding of the transfer relay R880. Accordingly, at this time the rotary magnet M906 is operated a number of times corresponding to the number of impulses in the third digit, whereby the wiper set is driven a corresponding number of steps in the rotary direction in order to select the corresponding contact set in the previously selected level.

At the conclusion of the third digit the line relay R860 is retained in its operated position in order to retain operated the hold relay R870, and shortly thereafter the transfer relay R880 restores. Upon restoring, the transfer relay R880 completes, at the contacts 881, an obvious path, including the contacts 873, for connecting ground potential to the winding of the trunk test relay R1030, whereby the idle or busy condition of the trunk terminated by the selected contact set is tested. More particularly, in the event the trunk terminated by the selected contact set is busy, ground potential appears upon the control conductor thereof and is applied to the control wiper 1014 of the wiper set, whereby an obvious path for short-circuiting the winding of the trunk test relay R1030 is completed, thereby positively to prevent operation of the latter relay. Also, upon restoring, the transfer relay R880 interrupts, at the contacts 882, the previously traced alternative holding circuit for energizing the winding of the transfer relay R920, thereby to cause the latter relay to restore shortly thereafter, the transfer relay R920 being of the slow-to-release type. Upon restoring, the transfer relay R920 completes, at the contacts 924, a path, including the contacts 872 and 1047, for connecting battery potential by way of the resistor 815 and the winding of the hunt relay R960 to the control

wiper 1013 of the wiper set. At this time the control wiper 1013 of the wiper set engages a contact having ground potential thereon, whereby an obvious circuit for energizing the winding of the hunt relay R960 is completed. The hunt relay R960 then operates to complete, at the contacts 962, an alternative circuit, including the grounded control conductor C813, the contacts 1031 and 1045, the contacts 910 of the set of switch springs S908 and the contacts 907, for energizing the rotary magnet M906. When thus energized the rotary magnet M906 operates, thereby to drive the wiper set an additional step in the rotary direction and to interrupt, at the contacts 907, the above-traced alternative circuit for energizing the rotary magnet M906. The rotary magnet M906 then restores, thereby to re-prepare, at the contacts 907, the circuit for energizing the rotary magnet M906. Accordingly, the rotary magnet M906 operates intermittently, thereby to drive the wiper set additional steps in the rotary direction, in the event the successive trunks in the selected level are tested as busy and until an idle trunk or the last trunk in this group is tested.

When an idle trunk in the group is tested by the control wiper 1014 of the wiper set, battery potential is encountered on the control conductor thereof, thereby to complete an obvious circuit for energizing the winding of the trunk test relay R1030 in order to cause the latter relay to operate. Upon operating, the trunk test relay R1030 completes, at the contacts 1032, an obvious circuit, including the grounded control conductor C813, for energizing the winding of the cut-through relay R1040, thereby to cause the latter relay to operate. Upon operating, the cut-through relay R1040 completes, at the contacts 1046, an obvious multiple holding circuit, including the grounded control conductor C813, for energizing the winding thereof, and interrupts, at the contacts 1045, a further point in the previously traced circuit for energizing the rotary magnet M906, thereby positively to arrest further operation of the latter magnet and consequently further rotation of the wiper set in the rotary direction. Also the cut-through relay R1040 interrupts, at the contacts 1041 and 1043, a normally completed path, including the contacts 856, 934 and 853, for connecting the resistor 1002 across the windings 832 and 834 of the repeating coil 830; and completes, at the contacts 1042 and 1044, a connection, including the contacts 853, 934 and 856 and the condenser 836, between the windings 832 and 834 of the repeating coil 830 and the line wipers 1011 and 1012 of the wiper set. Also the cut-through relay R1040 interrupts, at the contacts 1044', the previously traced path for applying ground potential to the control conductor C814 of the trunk 810, and completes, at the contacts 1043', an obvious connection between the control conductor C814 of the trunk 810 and the control wiper 1015 of the wiper set. Further the cut-through relay R1040 completes, at the contacts 1048, an obvious path for applying ground potential to the control wiper 1014 of the wiper set and an obvious multiple path for short-circuiting the winding of the trunk test relay R1030, thereby to cause the latter relay to restore. Also the cut-through relay R1040 interrupts, at the contacts 1042', the previously traced circuit for energizing the upper winding of the control relay R930. At this time, only the previously traced holding circuit for energizing the lower winding of the control relay R930 is com-

pleted, whereby the latter relay operates, the control relay R930 being of the differential type.

Upon operating, the control relay R930 completes, at the contacts 930, a connection, including the contacts 955 and 944 between the impulse conductor C904 and the upper winding of the control relay R940, for a purpose more fully explained hereinafter. It is noted that sixty ground impulses per minute are applied to the impulse conductor C904, for a purpose more fully explained hereinafter. Also the control relay R930 interrupts, at the contacts 934, the previously traced connection between the windings 832 and 834 of the repeating coil 830 and the line wipers 1011 and 1012 of the wiper set; completes, at the contacts 935, an obvious path, including the resistor 901 and the contacts 856 and 1044, for applying battery potential to the line wiper 1012 of the wiper set; and completes, at the contacts 931, an obvious path, including the contacts 853 and 1042, for applying ground potential to the line wiper 1011 of the wiper set. The application of ground and battery potentials, respectively, to the line wipers 1011 and 1012 and consequently to the respective negative and positive line conductors of the trunk seized by the wiper set causes the seized circuit to be rung, in a manner more fully explained hereinafter. Further the control relay R930 completes, at the contacts 931, 932 and 933, an alternative path for connecting the resistor 1002 across the windings 832 and 834 of the repeating coil 830, and completes, at the contacts 931 and 933, an obvious path, including the condenser 912, for connecting the generator conductor C903 across the windings 832 and 834 of the repeating coil 830, whereby ring-back tone current traverses the windings mentioned. The ring-back tone current traversing the windings 832 and 834 of the repeating coil 830 induces corresponding ring-back tone voltage in the windings 831 and 833 thereof, whereby ring-back tone current is returned over the trunk 810, the toll first selector 600, the trunk 570, the toll line circuit 200 and the toll line 201 to the toll switchboard in the remote exchange 20 in order to indicate to the operator thereat that the called circuit is being rung.

The next time ground potential is applied to the impulse conductor C904 the above-traced circuit for energizing the upper winding of the control relay R940 is completed, thereby to cause the latter relay to operate. Upon operating, the control relay R940 interrupts, at the contacts 946 and 942, the previously traced original circuit for energizing the lower winding of the control relay R930, and completes, at the contacts 945, an obvious alternative holding circuit, including the set of switch springs S911 and the contacts 876, for energizing the lower winding of the control relay R930. Also the control relay R940 interrupts, at the contacts 942, the previously traced holding circuit for energizing the lower winding of the control relay R950, and completes, at the contacts 941, an alternative holding circuit, including the contacts 952 and the grounded impulse conductor C904, for energizing the lower winding of the control relay R950. Further the control relay R940 interrupts, at the contacts 944, the above-traced circuit for energizing the upper winding thereof, and completes, at the contacts 943, an alternative circuit, including the set of switch springs S911 and the contacts 876, for energizing the upper winding thereof.

When ground potential is next removed from the impulse conductor C904 the previously traced alternative holding circuit for energizing the lower winding of the control relay R950 is interrupted, thereby to cause the latter relay to restore shortly thereafter, the control relay R950 being of the combination slow-to-operate and slow-to-release type. Upon restoring, the control relay R950 completes, at the contacts 953, an obvious connection, including the contacts 941, between the lower winding of the control relay R940 and the impulse conductor C904.

The next time ground potential is applied to the impulse conductor C904 the above-traced circuit for energizing the lower winding of the control relay R940 is completed. When both the upper and lower windings of the control relay R940 are thus energized the latter relay restores as it is of the differential type. Upon restoring, the control relay R940 interrupts, at the contacts 945, the previously traced holding circuit, including the set of switch springs S911 and the contacts 876, for energizing the lower winding of the control relay R930, and completes, at the contacts 946, an alternative holding circuit, including the contacts 957 and 938 and the impulse conductor C904, for energizing the lower winding of the control relay R930. When ground potential is next removed from the impulse conductor C904 the above-traced alternative circuit for energizing the lower winding of the control relay R930 is interrupted, thereby to cause the latter relay to restore. Upon restoring, the control relay R930 interrupts, at the contacts 931 and 935, the previously traced paths for applying ground and battery potentials to the line wipers 1011 and 1012 of the wiper set; interrupts, at the contacts 931, 932 and 933, the previously traced path for connecting the resistor 1002 across the windings 832 and 834 of the repeating coil 830; interrupts, at the contacts 931 and 933, the previously traced circuit for returning ring-back tone current over the windings 832 and 834 of the repeating coil 830; and recomplete, at the contacts 934, the previously traced connection between the windings 832 and 834 of the repeating coil 830 and the line wipers 1011 and 1012 of the wiper set. When ground and battery potentials are removed from the line wipers 1011 and 1012 of the wiper set the ringing operation in the seized circuit is arrested.

In the event the operator at the toll switchboard in the remote exchange 20 should wish to ringing the called circuit this may be accomplished by suitably controlling the associated equipment 220, thereby to effect the momentary restoration of the signal relay R210 in the toll line circuit 200 and consequently the momentary restoration of the line relay R860 in the toll second selector 800. When the line relay R860 restores it completes, at the contacts 862, a path, including the contacts 857 and 874, for applying ground potential to the contacts 1041', thereby to recomplete the previously traced multiple circuits for energizing the upper winding of the control relay R950 and the upper and lower windings of the control relay R930, whereby the control relay R950 operates shortly thereafter and the control relay R930 remains in its restored position, as previously explained. Upon operating, the control relay R950 completes, at the contacts 952 and 954, the previously traced holding circuit, including the contacts 942, the set of switch springs S911 and the contacts 876, for energizing the lower winding thereof, and interrupts, at the contacts 945 and 938, the previously traced holding circuit, including the contacts 957 and 938, for energizing the lower winding of the control relay R930.

tacts 951, the previously traced circuit for energizing the upper winding thereof. Also the control relay R950 completes, at the contacts 954 and 956, the previously traced circuit, including the contacts 942, the set of switch springs S911 and the contacts 876, for energizing the lower winding of the control relay R930, and interrupts, at the contacts 957, the previously traced original circuit for energizing the lower winding of the control relay R930. When the line relay R860 then re-operates it interrupts, at the contacts 862, the previously traced circuit for energizing the upper winding of the control relay R930, whereby the latter relay operates due to the completed holding circuit for energizing the lower winding thereof. The control relays R930, R940 and R950 then repeat the cycle of operation and restoration thereof in order to initiate a rering operation of the called circuit, in the manner previously explained.

In the foregoing explanation of the mode of operation of the switch mechanism 1010 to select an idle trunk in the group in the selected level, it was assumed that an idle trunk in the group mentioned was present to be selected. However, it may occur that all of the trunks in the group mentioned are busy at this time, in which event the wiper set is moved in the rotary direction to select the last trunk in the group mentioned. When the last trunk in this group is thus selected by the wiper set the control wiper 1013 of the wiper set engages a contact having no ground potential thereon, whereby the previously traced circuit for energizing the winding of the hunt relay R960 is interrupted in order to cause the latter relay to restore. Upon restoring, the hunt relay R960 interrupts, at the contacts 962, the previously traced circuit for energizing the rotary magnet M906, thereby positively to arrest further operation thereof and consequently further movement of the wiper set in the rotary direction. Also, at this time, ground potential appears upon the control conductor of the last trunk in the group mentioned and is applied to the control wiper 1014 of the wiper set, thereby to retain completed the previously mentioned path for short-circuiting the winding of the trunk test relay R1030. Accordingly, the trunk test relay R1030 remains in its restored position. Also, upon restoring, the hunt relay R960 completes, at the contacts 963, a connection, including the contacts 928, 1024 and 1044, between the impulse conductor C905 and the control conductor C814 of the trunk 810, 120 ground impulses per minute being applied to the impulse conductor C905. The interrupted ground potential thus applied to the control conductor C814 of the trunk 810 causes corresponding intermittent operation of the supervisory relay R550 in the toll line circuit 200 in order to render all-trunks-busy supervision to the operator at the switchboard in the remote exchange 20, in the manner previously explained.

The above-described operation of the toll second selector 800 takes place in order to select a trunk extending to an idle inward trunk circuit, such, for example, as the trunk 1070, extending to the inward trunk circuit 1100. Now assuming that the toll second selector 800 has operated in the manner described above to seize the trunk 1070 extending to the inward trunk circuit 1100, ground potential in the toll second selector 800 is applied to the control wiper 1014 of the wiper set and consequently to the control conductor C1073 of the trunk 1070, thereby to complete an obvious circuit, including the contacts 1121, for energizing the winding of the seizure relay 75

R1140 in the inward trunk circuit 1100, whereupon the latter relay operates. Also ground potential in the inward trunk circuit 1100 is applied by way of the contacts 1124 to the control conductor C1074 of the trunk 1070 and consequently to the control wiper 1015 of the wiper set of the toll second selector 800, thereby to retain restored the supervisory relay R550 in the toll line circuit 200, in the manner previously explained. Upon operating, the seizure relay R1140 completes, at the contacts 1142, an obvious path, including the contacts 1131, for applying battery potential by way of the winding of the cutoff relay R1120 to the control conductor C1173 of the trunk 1170, thereby to mark the rotary position of the trunk 1170 in the contact banks of the link finder switches having access thereto. Also the seizure relay R1140 completes, at the contacts 1141, an obvious multiple holding circuit for energizing the winding thereof, and completes, at the contacts 1143, an obvious path, including the contacts 1161 and 1132, for applying ground potential to the start conductor C1102 extending to the common start and level distributor circuit 1101, thereby to mark the level of the calling trunk 1170 to the link finder switches having access thereto and to initiate operation of the common start and level distributor circuit 1101.

At this point it is noted that the subsequent operation of the toll second selector 800 to effect a timed ringing cycle of operation of the called circuit, the inward trunk circuit 1100, causes operation of the ring relay R1150 and the consequent operation of the supervisory relay R1160 without effect at this time. Subsequently, when the ringing cycle is terminated the ring relay R1150 and the supervisory relay R1160 restore again without effect, at this time.

As previously noted, the application of ground potential to the start conductor C1102 initiates operation of the common start and level distributor circuit 1101, whereby the group of circuits, including the inward trunk circuit 1100, is locked in to be seized by one of the link finder switches and operation of the position distributor 1105 is initiated, whereby the call is distributed to a previously selected idle one of the operator positions at the switchboard having the talk key of an idle one of the link finder switches operated at this time. Assume that the first operator position 1201 at the switchboard in the tandem exchange 30 is idle, that the link illustrated is idle, that the talk key K1280 occupies its operated position, and that the position distributor 1101 has selected the first operator position 1201. In this case, the position distributor 1105 causes ground potential to be applied by way of the first operator position 1201 and the cable 1270 to the start conductor C1281 in order to effect operation of the start relay R1280 in the link finder switch 1200, the connect relay R1250 occupying its operated position at this time as a result of the operation of the talk key K1280. Upon operating, the start relay R1280 initiates operation of the link finder switch 1200, whereby the wiper set thereof seizes the trunk 1170 extending to the inward trunk circuit 1100, thereby to complete a connection from the first operator position 1201 to the trunk 1170 and consequently by way of the trunk 1070 to the toll second selector 800 on through the toll first selector 600, the trunk 570, the toll line circuit 200 and the toll line 201 to the toll switchboard in the remote exchange 20. Also ground potential in the link finder switch 1200 is applied by way of the con-

trol wiper 1206 thereof to the control conductor C1173 of the trunk 1170 in order to complete the previously mentioned circuit for energizing the winding of the cutoff relay R1120. When thus energized the cutoff relay R1120 operates to complete, at the contacts 1122, an obvious holding circuit, including the grounded control conductor C1173 of the trunk 1170, for energizing the winding thereof, and to complete, at the contacts 1123, an obvious circuit for energizing the winding of the control relay R1130 in order to cause the latter relay to operate. Upon operating, the control relay R1130 interrupts, at the contacts 1132, the previously mentioned path for applying ground potential to the start conductor C1102, thereby to effect the release of the common start and level distributor circuit 1101 and the position distributor 1105. Also the control relay R1130 completes, at the contacts 1133, an obvious holding circuit, including the contacts 1143 and 1161, for energizing the winding thereof. Further the cutoff relay R1120 interrupts, at the contacts 1124, the previously mentioned path for applying ground potential to the control conductor C1074 of the trunk 1070, whereby the control conductor C1074 is connected by way of the copper oxide rectifier 1126, the upper winding of the supervisory relay R1160, the control conductor C1174 of the trunk 1170, the control wiper 1207 of the link finder switch 1200, the contacts 1218 and 1244, C1293, apparatus, not shown, in the first operator position 1201 and the winding of the supervisory relay R1230 to battery. When ground potential is removed from and battery potential, by way of the winding of the supervisory relay R1230, is substituted therefor on the control conductor C1174 of the trunk 1170, the upper winding of the supervisory relay R550 in the toll line circuit 200 is deenergized in order to effect the operation of the latter relay, whereby answer supervision is rendered the operator at the toll switchboard in the remote exchange 20, in the manner previously explained.

The operator at the first operator position 1201 at the toll switchboard in the tandem exchange 30 is advised concerning the extension of the call and then operates the sending key set DK in order to cause digits to be registered by way of the sender link SL-1 in an idle one of the digit register and control circuits. More particularly, when the call is answered on the link illustrated at the first operator position 1201, the apparatus thereat controls the sender link SL-1 in order to cause the switch LF-1 to seize the cable 1285 extending to the link illustrated which is connected to the cable 1270 extending to the first operator position 1201. Also the switch SS-1 is controlled to select an idle digit register and control circuit, such, for example, as the circuit 1390. Accordingly, at the present time, the operation of the sending key set DK causes the digits to be registered in the digit register and control circuit 1390 by way of the sender link SL-1. The digit register and control circuit 1390 then operates in order to cause the registered digits to be transmitted by way of the sender link SL-1 and the cable 1286 to the toll selector switch 1300 forming a part of the link illustrated, whereby the toll selector switch 1300 and the succeeding switches in the toll switch train are operated. For example, the toll selector switch 1300 may be operated to select the trunk 1390 extending to the toll connector 1380 and then the toll connector 1380 may be operated to select the subscriber line 1381 extending to the subscriber sub-

station A. After all of the digits registered in the digit register and control circuit 1390 have been transmitted this circuit is released and the sender link SL-1 is controlled in order to effect the operation of the cut-in relay R1260 in the link finder switch 1200, whereby the link finder switch 1200 and the toll selector switch 1300 of the link illustrated are interconnected. After the subscriber at the called subscriber substation A answers the call and is advised that a toll call is being extended thereto, ordinarily the operator at the first operator position 1201 disconnects from the link finder switch 1200 by restoring the talk key K1280. At this time the connection from the toll switchboard in the remote exchange 20 is completed by way of the toll line 201, the toll line circuit 200, the trunk 570, the toll first selector 600, the trunk 810, the toll second selector 800, the trunk 1070, the inward trunk circuit 1100, the trunk 1170, the link finder switch 1200, the toll selector switch 1300, the trunk 1390, the toll connector 1380 and the subscriber line 1381 to the called subscriber substation A in the tandem exchange 30, independently of the position equipment at the first operator position 1201.

When the talk key K1280 of the link finder switch 1200 is restored in order to disconnect the link illustrated from the first operator position 1201, the connect relay R1250 and the start relay R1240 restore. Upon restoring, the start relay R1240 interrupts, at the contacts 1244, the previously traced path for applying battery potential by way of the winding of the supervisory relay R1230 to the control wiper 1207; and completes, at the contacts 1245, an obvious alternative path for applying battery potential by way of the rear supervisory lamp L1267 and the contacts 1218 to the control wiper 1207, whereby the supervisory relay R550 in the toll line circuit 200 is retained in its operated position, as previously explained.

At this time, in the event the subscriber at the called subscriber substation A in the tandem exchange 30 should require the attention of the operator at the first operator position 1201 at the toll switchboard in the tandem exchange 30, he may attract her attention by intermittently operating the switchhook thereat. This operation of the switchhook at the called subscriber substation A causes operation of the toll connector 1380, whereby ground potential is intermittently applied to the control conductor of the trunk 1390 and consequently to the control wiper 1304 of the toll selector switch 1300, thereby to complete a circuit, including the contacts 1263 and the contacts 1275 of the talk key K1280, for flashing the front supervisory lamp L1276. The flashing of the front supervisory lamp L1276, following the operation of the switchhook at the called subscriber substation A, indicates to the operator at the first operator position 1201 that the subscriber at the called subscriber substation A requires supervision. The operator at the first operator position 1201 then reoperates the talk key K1280, whereby the link illustrated is reconnected via the cable 1270 to the first operator position 1201. At this time, in the event it is necessary for the operator at the first operator position 1201 at the switchboard in the tandem exchange 30 to recall the operator at the toll switchboard in the remote exchange 20, this may be accomplished by operating the ring key at the first operator position 1201, whereby ringing current is projected over the line wipers 1202 and 1203 of the link finder switch 1200 and conse-

quently over the line conductors C1171 and C1172 of the trunk 1170. The ringing current projected over the line conductors C1171 and C1172 of the trunk 1170 completes an obvious circuit for energizing in multiple the upper and lower windings of the ring relay R1150, thereby to cause the latter relay to operate. Upon operating, the ring relay R1150 completes, at the contacts 1151, an obvious circuit for energizing the lower winding of the supervisory relay R1160, thereby to cause the latter relay to operate. Upon operating, the supervisory relay R1160 completes, at the contacts 1162, an obvious path, including the copper oxide rectifier 1126, for applying ground potential to the control conductor C1074 of the trunk 1070 in order to effect restoration of the supervisory relay R550 in the toll line circuit 200 and the consequent transmission of a ring or recall signal over the toll line 201 to the toll switchboard in the remote exchange 20. Also, upon operating, the supervisory relay R1160 completes, at the contacts 1162, a series circuit for energizing the upper winding of the supervisory relay R1160 and the winding of the supervisory relay R1230, this circuit extending from ground by way of the contacts 1162, the upper winding of R1160, the control conductor C1174 of the trunk 1170, the control wiper 1207 of the link finder switch 1200, the contacts 1213 and 1244, C1293 and the winding of R1230 to battery. When this series circuit is completed the supervisory relay R1230 operates; however, the upper winding of the supervisory relay R1160 is not sufficiently energized due to the high series resistance of the winding of the supervisory relay R1230 to retain the supervisory relay R1160 in its operated position subsequent to the restoration of the ring relay R1150. Upon operating, the supervisory relay R1230 completes, at the contacts 1231, an obvious circuit, including C1285 and the contacts 1246, for illuminating the rear supervisory lamp L1267 in order to remind the operator at the first operator position 1201 that the ring key theretofore is operated.

The operator at the first operator position 1201 operates the ring key theretofore back and forth a number of times in order to cause intermittent operation of the ring relay R1150. Finally, when the ring key at the first operator position 1201 is restored, the ring relay R1150 restores, thereby to interrupt, at the contacts 1151, the previously mentioned circuit for energizing the lower winding of the supervisory relay R1160. The supervisory relay R1160 then restores in order to interrupt, at the contacts 1162, the previously traced circuit for energizing the upper winding thereof in series with the winding of the supervisory relay R1230. Also, upon restoring, the supervisory relay R1160 interrupts, at the contacts 1162, the previously traced path for applying ground potential to the control conductor C1074 of the trunk 1070, thereby to effect reoperation of the supervisory relay R550 in the toll line circuit 200 and the consequent transmission of the answer signal over the toll line 201 to the toll switchboard in the remote exchange 20, in the manner previously explained.

When the operator at the toll switchboard in the remote exchange 20 receives the recall signal she reenters the connection and converses with the operator at the first operator position 1201 in the tandem exchange 30. Subsequently the operator at the toll switchboard in the remote exchange 20 disconnects from the established connection; and the operator at the first operator

position 1201 disconnects from the established connection by restoring the talk key K1280, as previously explained.

In the event the subscriber at the called subscriber substation A first releases the established connection by replacing the receiver of the telephone instrument thereat upon its associated switchhook, the toll connector 1380 operates in order to effect the illumination of the front supervisory lamp L1276, in the manner previously explained. The operator at the first operator position 1201 then reenters the connection by operating the talk key K1280 and ascertains that the subscriber at the called subscriber substation A has initiated the release of the established connection. Then the operator at the first operator position 1201 operates the ring key theretofore in order to cause the transmission of the ring or ring-off signal over the toll line 201 to the toll switchboard in the remote exchange 20, in the manner previously explained. The operator at the first operator position 1201 then effects the release of the link finder switch 1200 and the toll selector switch 1300 by operating the release keys in the associated position equipment. When the toll selector switch 1300 is thus released the toll connector 1380 is released, whereby the subscriber line 1381 extending to the called subscriber substation A is marked as idle to the switches having access thereto.

The operator at the toll switchboard in the remote exchange 20 then effects the release of the toll line 201 and the consequent release of the toll line circuit 200 and the toll first selector 600, in the manner previously explained. When the toll first selector 600 is released the toll second selector 800 is released. When the toll second selector 800 is released the previously traced circuit for energizing the winding of the seizure relay R1140 is interrupted, thereby to cause the latter relay to restore. Similarly, when the link finder switch 1200 is released the previously traced circuit for energizing the winding of the cutoff relay R1120 is interrupted, thereby to cause the latter relay to restore. Upon restoring, the cutoff relay R1120 interrupts, at the contacts 1123, the previously mentioned circuit for energizing the winding of the control relay R1130, thereby to cause the latter relay to restore. At this time the inward trunk circuit 1100 is completely released and the trunks 1070 and 1170 extending thereto are marked as idle to the switching apparatus having access thereto.

At this point it is noted that, when the operator at the first operator position 1201 first receives the release supervision from the called subscriber substation A in the tandem exchange 30 and then reenters the connection by operating the talk key K1280, she may release the link finder switch 1200 and the toll selector switch 1300 without operating the ring key in the associated position equipment, in the manner explained above. In this event, when the link finder switch 1200 is released it interrupts the previously traced circuit for energizing the winding of the cutoff relay R1120 in the inward trunk circuit 1100, thereby to cause the latter relay to restore. Upon restoring, the cutoff relay R1120 completes, at the contacts 1124, an obvious path for applying ground potential to the control conductor C1074 of the trunk 1070, thereby to effect the restoration of the supervisory relay R550 in the toll line circuit 200 and the consequent transmission of a release signal over the toll line 201 to the toll switchboard in the remote

exchange 20. The operator at the toll switchboard in the remote exchange 20 then reenters the connection and effects the release of the toll line circuit 200, the toll first selector 600 and the toll second selector 800, all in the manner previously explained. When the toll second selector 800 is released the inward trunk circuit 1100 is released, as previously explained.

On the other hand, the release of the established connection between the toll switchboard in the remote exchange 20 and the called subscriber substation A in the tandem exchange 30 may be initiated by the operator at the toll switchboard in the remote exchange 20. This may be accomplished by the operator at the toll switchboard in the remote exchange 20 by the operation of the associated position equipment in order to effect momentary restoration of the line relay R860 in the toll second selector 800, whereby the toll second selector 800 is operated through a rering cycle, in the manner previously explained. Accordingly, the toll second selector 800 causes ringing current to be projected for a timed interval over the line wipers 1011 and 1012 of the switch mechanism 1010. More particularly, the ringing current traverses the line conductors C1071 and C1072 of the trunk 1070, thereby to complete an obvious multiple circuit for energizing the upper and lower windings of the ring relay R1150. When thus energized the ring relay R1150 operates to complete, at the contacts 1151, the previously mentioned circuit for energizing the lower winding of the supervisory relay R1160 in order to cause the latter relay to operate. Upon operating, the supervisory relay R1160 completes, at the contacts 1162, the previously mentioned path for applying ground potential by way of the copper oxide rectifier 1126 to the control conductor C1074 of the trunk 1070, whereby the supervisory relay R550 in the toll line circuit 200 restores in order to transmit a ringback signal over the toll line 201 to the toll switchboard in the remote exchange 20. Also the supervisory relay R1160 completes, at the contacts 1162, a holding circuit, including the control conductor C1174 of the trunk 1170, the control wiper 1207 of the link finder switch 1200 and the contacts 1218 and 1245, for energizing the upper winding thereof and for illuminating the rear supervisory lamp L1267. After the toll second selector 800 operates through the rering cycle in order to cause one splash of ringing current to be transmitted over the line conductors of the trunk 1070 the ring relay R1150 restores and the supervisory relay R1160 is retained in its operated position.

The illumination of the rear supervisory lamp L1267 indicates to the operator at the first operator position 1201 at the switchboard in the tandem exchange 30 that the established connection requires supervision and that the supervision was initiated over the link finder switch 1200 by way of the calling end of the established connection. The operator at the first operator position 1201 then operates the talk key K1280 in order to reenter the established connection and to effect the reoperation of the start relay R1240 and the connect relay R1250. Upon reoperating, the start relay R1240 interrupts, at the contacts 1245, the previously traced holding circuit for energizing the upper winding of the supervisory relay R1160 and for illuminating the rear supervisory lamp L1267, whereby the supervisory relay R1160 restores and the rear supervisory lamp L1267 is extinguished. At this time

the operator at the first operator position 1201 at the switchboard in the tandem exchange 30 converses with the operator at the toll switchboard in the remote exchange 20. The subsequent handling of the connection, as well as the release thereof, is performed in the manner previously explained.

On the other hand, the operator at the toll switchboard in the remote exchange 20 may initiate the release of the established connection extending to the called subscriber substation A in the tandem exchange 30 merely by effecting the release of the toll line 201, the toll line circuit 200, the toll first selector 600 and the toll second selector 800, all in the manner previously explained. In this event, when the toll second selector 800 is released, the previously traced circuit for energizing the winding of the seizure relay R1140 is interrupted in order to cause the latter relay to restore. Upon restoring, the seizure relay R1140 completes, at the contacts 1144, an obvious path, including the contacts 1161, for applying ground potential to the control conductor C1174 of the trunk 1170, thereby to complete the previously traced circuit for illuminating the rear supervisory lamp L1267. The operator at the first operator position 1201 then reenters the connection by operating the talk key K1280 and then effects the release of the link finder switch 1200, the toll selector switch 1300 and the toll connector 1380, all in the manner previously explained. When the link finder switch 1200 is thus released the inward trunk circuit 1100 is released, in the manner previously explained.

Considering now in greater detail the release of the toll second selector 800, it is pointed out that, when the toll first selector 600 is released, the previously traced circuit for energizing the winding of the line relay R860 in the toll second selector 800 is interrupted in order to cause the latter relay to restore. Upon restoring, the line relay R860 interrupts, at the contacts 861, the previously mentioned circuit for energizing the winding of the hold relay R870, thereby to cause the latter relay to restore shortly thereafter, the hold relay R870 being of the slow-to-release type. Also, when the toll first selector 600 is released ground potential is removed from the control conductor C813 of the trunk 810, thereby to interrupt the previously traced holding circuit for energizing the winding of the cut-through relay R1040 in order to cause the latter relay to restore. Upon restoring, the hold relay R870 interrupts, at the contacts 871, the previously traced holding circuit for energizing the upper winding of the control relay R1020, thereby to cause the latter relay to restore. Further, the hold relay R870 completes, at the contacts 875, a circuit, including the contacts 857 and 862 and the set of switch springs S820, for energizing the release magnet M816, thereby to cause the latter magnet to operate and release the wiper set of the switch mechanism 1010, the wiper set being returned to its normal vertical and rotary positions. When the wiper set is thus released the sets of switch springs S817 and S820 are actuated. More particularly, the set of switch springs S820 is actuated into disengagement, thereby to interrupt the previously traced circuit for energizing the release magnet M816. At this time the toll second selector 800 is completely released.

In the above-described operation of the toll second selector 800, had the wiper set been operated to one of the specified levels, such, for ex-

ample, as the level in which the trunk 1060 extending to the trunk circuit 1110 terminates, the sets of switch springs S821 and S911 would have been operated. At this point it is again noted that the trunk circuit 1110 terminating the trunk 1060 also terminates the trunk line 1065 extending to the distant exchange 40. More particularly, the set of switch springs S911 is actuated into disengagement, thereby to interrupt the previously traced holding circuit for energizing the lower winding of the control relay R950 and the previously traced multiple circuits for energizing the upper and lower windings of the control relay R930, whereby the control relay R930 remains in its restored position and the control relay R950 restores shortly thereafter, the latter relay being of the combination slow-to-operate and slow-to-release type. In this event, operation of the rotary magnet M906 is initiated under the control of the trunk test relay R1030, in the manner previously explained, whereby the wiper set is moved step by step in the rotary direction in order to test the successive trunks in the selected level. When an idle trunk in the selected level, such, for example, as the trunk 1060 extending to the trunk circuit 1110 is tested, the trunk test relay R1030 operates in order to effect operation of the cut-through relay R1040, in the manner previously explained. Upon operating the cut-through relay R1040 interrupts, at the contacts 1045, the previously traced circuit for energizing the rotary magnet M906, thereby positively to arrest further operation of the latter magnet and further movement of the wiper set in the rotary direction. At this point it is noted that the trunk 1060 is marked as idle to the toll second selector 800 by the application of battery potential upon the control conductor thereof. Also, in this case, upon operating, the trunk test relay R1030 completes, at the contacts 1032, a circuit, including the grounded control conductor C813 and the set of switch springs S321, for energizing the winding of the switch-through relay R850, thereby to cause the latter relay to operate. Also, upon operating, the cut-through relay R1040 completes, at the contacts 1048, the previously traced path for short-circuiting the winding of the trunk test relay R1030, thereby to cause the latter relay to restore.

Upon operating, the switch-through relay R850 interrupts, at the contacts 851 and 854, the previously traced circuit for energizing the winding of the line relay R860, thereby to cause the latter relay to restore. Also, the switch-through relay R850 completes, at the contacts 852 and 855, a direct connection, including the contacts 1042 and 1044, between the line conductors of the trunk 810 and the line wipers 1011 and 1012 of the wiper set, whereby the grounded control conductor C212 in the toll line circuit 200 is connected through the windings of the seizure relay R530 and the pad relay R350 therein directly through the toll first selector 600 to the line conductors of the trunk 1060 and consequently through the line relay in the trunk circuit 1110 to battery. Also, the switch-through relay R850 interrupts, at the contacts 853 and 856, the normally completed connections between the windings 832 and 834 of the repeating coil 830 and the line wipers 1011 and 1012 of the wiper set. At this time ground potential in the trunk circuit 1110 is applied by way of the control conductor of the trunk 1060, the control wiper 1015 of the wiper set and the contacts 1043' to the control

conductor C814 of the trunk 810, whereby ground potential is retained upon the control conductor C574 of the trunk 570 in order to retain energized the upper winding of the supervisory relay R550 in the toll line circuit 200.

- Upon restoring, the line relay R850 effects the restoration of the hold relay R870 shortly thereafter. At this time the toll line circuit 200 is connected directly through the toll first selector 600 and the toll second selector 800 to the trunk 1060 extending to the trunk circuit 1110; and therefrom by way of the trunk line 1065 to automatic switching apparatus in the distant exchange 40. At this time, digits received in the toll line circuit 200 may be repeated therefrom directly through the toll first selector 600 and the toll second selector 800 to the trunk circuit 1110 and consequently over the trunk line 1065 to the automatic switching apparatus in the distant exchange 40. Subsequently, the automatic switching apparatus in the distant exchange 40 may be selectively controlled to set up a connection therein, in accordance with conventional practice. The release of the toll second selector 800, when it occupies its switch-through position as explained above, is effected when the toll first selector 600 is released in order to cause ground potential to be removed from the control conductor C813 of the trunk 810. When ground potential is removed from the control conductor C813 of the trunk 810 the previously traced multiple circuits for energizing the windings of the switch-through relay R850 and the cut-through relay R1040 are interrupted in order to cause these relays to restore. Upon restoring, the switch-through relay R850 completes, at the contacts 857, the previously traced circuit for energizing the release magnet M816, thereby to cause the latter magnet to operate and release the wiper set of the switch mechanism 1010. The remainder of the release of the toll second selector 800 is the same as that previously explained.

- In the foregoing explanation of the mode of operation of the toll second selector 800 to select an idle trunk in the previously selected level, it is pointed out that, should the wiper set of the switch mechanism 1010 be driven across the entire level of contact sets eleven steps in the rotary direction without testing a trunk in the selected level as idle, the ground potential is removed from the control wiper 1013 of the wiper set, whereby the hunt relay R960 restores. Upon restoring, the hunt relay R960 interrupts, at the contacts 962, the previously traced circuit for energizing the rotary magnet M906 in order positively to prevent further operation thereof, and completes, at the contacts 963, the previously traced path for connecting 120 ground impulses per minute to the control conductor C814 of the trunk 810, thereby to cause the supervisory relay R550 in the toll line circuit 200 to repeat the all-trunks-busy signal over the toll line 201 to the toll switch-board in the remote exchange 20.

Call from the tandem exchange to the remote exchange

- It is noted that the operator at one of the operator positions, such, for example, as the first operator position 1201 in the tandem exchange 30 may answer a call which is to be completed in the remote exchange 20. For example, the subscriber at the calling subscriber substation A may initiate a call and extend the same over the local switch train, not shown, and the associated C. L. R. equipment, not shown; and the call may

be answered at the first operator position 1201 via the link finder switch 1200 of the switching link illustrated. In this event, when the subscriber at the calling subscriber substation A advises the operator at the first operator position 1201 that the call is to be completed in the remote exchange 20, the operator at the first operator position 1201 proceeds to set up the directory number of the called subscriber substation in the remote exchange 20 on the sending key set DK. When the call mentioned is answered on the link finder switch 1200 and prior to the operation of the sending key set DK, the sender link SL-1 operates in order to cause the switch LF-1 to find the cable 1286 extending to the toll selector switch 1300 and to cause the switch SS-1 to seize an idle digit register and control circuit, such, for example, as the circuit 1390, all in the manner previously explained. When the operator at the first operator position 1201 operates the sending key set DK in accordance with the digits of the directory number of the called subscriber substation in the remote exchange 20, the digits are first registered in the digit register and control circuit 1390 and are then transmitted therefrom over the sender link SL-1 and the cable 1286 to the toll selector switch 1300. The first digit transmitted to the toll selector switch 1300 causes operation thereof, whereby the latter switch first selects the group of trunks, including the trunk 560, and then operates automatically to select an idle trunk in the group mentioned.

For purpose of illustration, assuming that the trunk 560 extending to the toll line circuit 200 is the first idle trunk in the group mentioned, the toll selector switch 1300 operates to select the trunk 560. At this point it is noted that the trunk 560 is marked as idle to the toll selector switch 1300 by the application of battery potential via the winding of the seizure relay R360 and the contacts 521 and 544 to the control conductor C563 thereof. When the toll selector switch 1300 seizes the trunk 560 ground potential therein is applied to the control conductor C563 thereof, thereby to complete a circuit substantially identical to that previously traced for energizing the winding of the seizure relay R360 in the toll line circuit 200. When thus energized the seizure relay R360 operates to complete, at the contacts 361, an obvious path, including the resistor 308, for applying battery potential to the pad control conductor C201, thereby to effect control of the pad 206. Also the seizure relay R360 completes, at the contacts 362, obvious multiple circuits for energizing the windings of the switch relay R320 and the rering relay R410, thereby to cause these relays to operate. Further the seizure relay R360 completes, at the contacts 363, an obvious circuit, including the contacts 431 and the resistor 309, for energizing the winding of the digit relay R330 in order to cause the latter relay to operate. Upon operating, the switch relay R320 interrupts, at the contacts 325 and 327, the previously traced normally completed connection between the control conductor C212 and the windings 302 and 304 of the repeating coil 300; and completes, at the contacts 322, 324, 326 and 328, a loop circuit for energizing the windings of the line relay R440, this circuit extending from ground by way of the lower winding of R440, the contacts 435 and 328, the winding 304 of the repeating coil 300 and the contacts 324 to the line conductor C562 of the trunk 560, and from battery by way of the upper winding of R440, the contacts 434 and 326,

the winding 302 of the repeating coil 300 and the contacts 322 to the line conductor C561 of the trunk 560. The line conductors of the trunk 560 are connected together by way of a bridge

5 in the sender link SL-1. More particularly, the line conductors of the trunk 560 are connected by way of the line wipers 1302' and 1303' of the toll selector switch 1300 and the line conductors C1252 and C1253 in the cable 1286 to the line wipers 1322 and 1323 of the switch LF-1; the line wipers 1322 and 1323 of the switch LF-1 being connected together by way of the bridge in the sender link SL-1, including the contacts controlled by the armatures 1311, 1321 and 1331.

15 When the line relay R440 is thus energized it operates. Also, upon operating, the switch relay R320 interrupts, at the contacts 321 and 323, the previously traced normally completed connection between the windings 302 and 304 of the repeating coil 300 and the line conductors C571 and C572 of the trunk 570 extending to the toll first selector 600.

Upon operating, the digit relay R330 completes, at the contacts 331, an obvious circuit for energizing the winding of the shunt relay R340, thereby to cause the latter relay to operate. Upon operating, the shunt relay R340 completes, at the contacts 341, an obvious path for short-circuiting the winding 302 of the repeating coil 300, thereby to improve impulsing between the sender link SL-1 and the line relay R440 in the toll line circuit 200.

Upon operating, the line relay R440 completes, at the contacts 441, an obvious path for short-circuiting the winding of the digit relay R330, thereby to cause the latter relay to restore and interrupt, at the contacts 331, the previously mentioned circuit for energizing the winding of the shunt relay R340, whereupon the latter relay restores shortly thereafter. Upon restoring, the shunt relay R340 interrupts, at the contacts 341, the previously mentioned path for short-circuiting the winding 302 of the repeating coil 300. Also the line relay R440 interrupts, at the contacts 443, the previously traced path, including the contacts 434 and 552, for applying ground potential to the control conductor C215, and completes, at the contacts 442, an obvious path, including the resistor 310 and the contacts 434 and 552, for applying battery potential to the control conductor C215. The battery potential applied to the control conductor C215 is connected by way of the retard coil 213 and the intermediate winding of the signal relay R210 to the simplex conductor C214 and therefrom by way of the winding 203 of the repeating coil 202 to the line conductors of the toll line 201, whereby the automatic switching equipment 220 in the remote exchange 20 is rendered responsive to digits transmitted thereto. At this time the toll line circuit 200 is in readiness to receive digits transmitted thereto over the trunk 560 through the toll selector switch 1300 from the sender link SL-1. The digit register and control equipment 1390 then controls the pulse relay R4320 in the sender link SL-1 in accordance with the next digit, whereby the previously mentioned bridge is controlled at the contacts 1321 in order to cause the line relay R440 in the toll line circuit 200 to follow the impulses of the digit mentioned. Each time the line relay R440 restores it interrupts, at the contacts 442, the previously traced path for applying battery potential to the control conductor C215, and completes, at the contacts 443, the previously traced path for ap-

plying ground potential to the control conductor C215. Similarly, each time the line relay R440 operates, it interrupts, at the contacts 443, the previously traced path for applying ground potential to the control conductor C215, and re-completes, at the contacts 442, the previously traced path for applying battery potential to the control conductor C215. Thus the line relay R440 follows the impulses of the digit mentioned and repeats a corresponding number of alternate ground and battery impulses over the control conductor C215 and consequently over the simplex conductor C214 and the line conductors of the toll line 201 to the automatic switching equipment 220 in the remote exchange 20 in order selectively to control operation of the latter equipment. Also each time the line relay R440 restores and then reoperates it interrupts and then re-completes, at the contacts 441, the previously traced path for short-circuiting the winding of the digit relay R330, thereby to cause the latter relay to follow the impulses of the digit mentioned. Each time the digit relay R330 operates and restores it completes and then interrupts, at the contacts 331, the previously mentioned circuit for energizing the winding of the shunt relay R340, thereby to cause the latter relay to operate and remain operated during impulsing, the shunt relay R340 being of the slow-to-release type. Upon operating, the shunt relay R340 completes, at the contacts 341, the previously traced path for short-circuiting the winding 302 of the repeating coil 300.

At the conclusion of the digit mentioned the line relay R440 remains operated in order to effect the restoration of the digit relay R330 and the restoration of the shunt relay R340 shortly thereafter. The sender link SL-1 is controlled by the digit register and control equipment 1390 to send a number of digits to the toll line circuit 200 which are repeated over the simplex conductor C214 and the line conductors of the toll line 201 to the automatic switching equipment 220 in the remote exchange 20, in the manner explained above.

After all of the digits registered in the digit register and control equipment 1390 have been transmitted by the sender link SL-1 the control relay R1330 and the loop test relay R1340 operate in order to cause battery potential to be applied by way of the resistor R1, the contacts 1332 and 1313, the wiper 1325 of the switch LF-1, C1289 and the control wiper 1304' of the toll selector switch 1300 to the control conductor C564 of the trunk 560. This application of battery potential to the control conductor C564 completes an obvious circuit, including the contacts 432, 463 and 451, for energizing the upper winding of the cutoff relay R430 in order to cause the latter relay to operate. Further the sender link SL-1 effects operation of the cut-in relay R1260 in the link finder switch 1200, thereby to complete an operative connection between the link finder switch 1200 and the toll selector switch 1300 in order to complete an operative connection between the calling subscriber substation A, via the link finder switch 1200, and the automatic switching equipment 220 in the remote exchange 20, via the toll selector switch 1300.

Upon operating, the cutoff relay R430 completes, at the contacts 438, an obvious holding circuit, including the contacts 363, for energizing the lower winding thereof, interrupts, at the contacts 432, the previously traced operating circuit for energizing the upper winding thereof, and

completes, at the contacts 431, an obvious path including the contacts 464, for applying ground potential to the control conductor C564 of the trunk 560. The application of ground potential to the control conductor C564 of the trunk 560 completes a circuit, including the control wiper 1304' of the toll selector switch 1300, the contacts 1263, the contacts 1274 of the talk key K1280 and the conductor C1187, for illuminating the front supervisory lamp L1276, thereby to indicate to the operator at the first operator position 1201 that the connection has been extended by the automatic switching equipment 220 in the remote exchange 20 and that shortly thereafter the idle or busy condition of the called subscriber substation will be tested. Also the cutoff relay R430 interrupts, at the contacts 434 and 436, the previously traced loop circuit for energizing in series the upper and lower windings of the line relay R440, thereby to cause the latter relay to restore, and interrupts, at the contacts 437, the previously traced circuit for energizing the winding of the digit relay R330, thereby to cause the latter relay to restore. Further the cutoff relay R430 prepares, at the contacts 433, a circuit traced hereinafter for energizing the winding of the identity relay R420, and prepares, at the contacts 435, a circuit traced hereinafter for energizing the winding of the rering relay R370. Also the cutoff relay R430 interrupts, at the contacts 434', the previously traced original path for applying battery potential by way of the resistor 310 to the control conductor C215, and completes, at the contacts 433', an alternative path, including the contacts 412 and 552, for applying battery potential by way of the resistor 310 to the control conductor C215. Upon restoring, the digit relay R330 effects the restoration of the shunt relay R340 shortly thereafter. Upon restoring, the shunt relay R340 interrupts, at the contacts 341, the previously mentioned path for short-circuiting the winding 302 of the repeating coil 300.

The automatic switching equipment 220 in the remote exchange 20 tests the idle or busy condition of the subscriber line extending to the called subscriber substation, and the sender link SL-1 and the digit register and control circuit 1390 in the tandem exchange 30 are automatically released. In the event the called subscriber substation is busy, the automatic switching equipment 220 in the remote exchange 20 operates in order to cause 120 ground impulses per minute to be returned over the line conductors of the toll line 201 and consequently via the simplex conductor C214 to the intermediate winding of the signal relay R210, whereby the latter relay operates and restores intermittently. Each time the signal relay R210 operates and restores it completes and then interrupts, at the contacts 211, an obvious circuit, including the control conductor C212 and the contacts 329, 342 and 431', for energizing the upper winding of the control relay R460, whereby the latter relay operates and then restores. Accordingly, the control relay R460 follows the intermittent operation of the signal relay R210. Each time the control relay R460 operates and restores it interrupts and then re-completes, at the contacts 464, the previously mentioned path for applying ground potential to the control conductor C564 of the trunk 560. The intermittent application of ground potential to the control conductor C564 of the trunk 560 completes a circuit, including the control wiper 1304' of the toll selector switch 1300, the contacts 1263, the contacts 1274 of the talk key K1280 and the

conductor C1187 for flashing the front supervisory lamp L1276 in order to indicate to the operator at the first operator position 1201 that the called subscriber substation in the remote exchange 20 is busy at this time. The operator at the first operator position 1201 then proceeds to release the toll selector switch 1300 in order to effect the release of the toll line circuit 200 and the consequent release of the automatic switching equipment 220 in the remote exchange 20, in a manner more fully explained hereinafter. Further the operator at the first operator position 1201 advises the subscriber at the calling subscriber substation A in the tandem exchange 30 that the desired connection cannot be had immediately due to the busy condition of the called subscriber substation in the remote exchange 20 at this time.

Now assuming that the automatic switching equipment 220 in the remote exchange 20 tests the called subscriber substation therein as idle, ringing current is projected over the subscriber line extending thereto, in accordance with conventional practice. Subsequently, when the subscriber at the called subscriber substation in the remote exchange 20 answers the call, the automatic switching equipment 220 operates in order to cause ground potential to be returned over the line conductors of the toll line 201 and consequently via the simplex conductor C214 to the intermediate winding of the signal relay R210, whereby the latter relay operates. Upon operating, the signal relay R210 completes, at the contacts 211, the previously mentioned path for applying ground potential to the control conductor C212, thereby to complete the previously traced circuit for energizing the upper winding of the control relay R460 in order to cause the latter relay to operate. Upon operating, the control relay R460 interrupts, at the contacts 464, the previously traced path for applying ground potential to the control conductor C564 of the trunk 560, thereby to interrupt the previously traced circuit for illuminating the front supervisory lamp L1276. When the front supervisory lamp L1276 is thus extinguished it indicates to the operator at the first operator position 1201 that the call has been answered at the called subscriber substation in the remote exchange 20. The operator at the first operator position 1201 then advises the subscriber at the calling subscriber substation A in the tandem exchange 30 that he may proceed with the conversation and then retires from the established connection by restoring the talk key K1280.

Reconsidering now the operation of the automatic switching equipment 220 in the remote exchange 20 in response to the digits repeated thereto over the toll line 201 by the toll line circuit 200, it is noted that the automatic switching equipment 220 may perform a trunk hunting operation in response to a digit received over the toll line 201 which requires considerable time and a time interval greater than that between digits received over the toll line 201. In this event, after a particular digit is received, following which the reception of the succeeding digit should be delayed, the automatic switching equipment 220 operates in order to cause ground potential to be applied to the line conductors of the toll line 201 for the necessary time interval while the trunk hunting operation is being performed. This application of ground potential to the line conductors of the toll line 201 and consequently via the simplex conductor C214 to the intermediate winding of the signal relay R210

causes operation of the latter relay. Upon operating, the signal relay R210 completes, at the contacts 211, an obvious path for applying ground potential to the control conductor C212, thereby to complete a circuit, including the contacts 329, 342, 439 and 474, for energizing the lower windings of the control relays R460 and R470 in multiple. Also the application of ground potential to the control conductor C212 completes a circuit, including the contacts 329, 342, 439, 476, 466 and 542, for energizing in multiple the upper winding of the control relay R470. When the lower winding of the control relay R460 is thus energized the latter relay operates; and when both the upper and lower windings of the control relay R470 are thus energized the latter relay remains restored, the control relay R470 being of the differential type.

Upon operating, the control relay R460 interrupts, at the contacts 463, the previously traced path for applying ground potential by way of the upper winding of the cutoff relay R430 to the control conductor C564 of the trunk 560, and completes, at the contacts 462, an obvious path, including the contacts 432, for applying battery potential by way of the resistor 401 to the control conductor C564 of the trunk 560. The application of battery potential to the control conductor C564 of the trunk 560 completes a circuit, including the control wiper 1304 of the toll selector switch 1300, the wiper 1325 of the switch LF-1, the contacts 1313 and the armature 1341 and the back contacts associated therewith, for energizing the winding of the delay pulsing relay R1350 in the sender link SL-1. When thus energized the delay pulsing relay R1350 operates to complete, at the armature 1351 and the front contacts associated therewith, an obvious alternative circuit for energizing the winding of the pulse relay R1320, thereby to retain the latter relay in its operated position. The operated pulse relay R1320 retains completed, at the contacts 1321, the previously traced bridge, in the sender link SL-1 for retaining completed the loop circuit extending to the line relay R440 in the toll line circuit 200, whereby the latter relay is retained in its operated position. Also, upon operating, the delay pulsing relay R1350 interrupts, at the contacts associated with the armature 1351, the previously traced path for applying battery potential by way of the winding of the pulse relay R1320 to the wiper 1305 of the switch SS-1, thereby to interrupt the previously mentioned circuit for energizing the winding of the pulse relay R1320 in the sender link SL-1 in series with the winding of the delay pulse relay R1340 in the digit register and control circuit 1390, whereupon the delay pulse relay R1340 restores. Upon restoring, the delay pulse relay R1340 arrests further operation of the digit register and control circuit 1390 at the present time.

Also, upon operating, the delay pulsing relay R1350 completes, at the armature 1352, an obvious circuit for energizing the winding of the control relay R1360, thereby to cause the latter relay to operate. Upon operating, the control relay R1360 completes, at the armature 1361, an obvious circuit for energizing the winding of the control relay R1370 and for setting into vibration the associated weighted armature, whereby the circuit mentioned for energizing the winding of the control relay R1370 is completed intermittently. In the event the delay pulsing relay R1350 remains operated for a predetermined time,

interval, retaining the control relay R460 in its operated position, vibration of the weighted armature 1361 ceases and the winding of the control relay R470 is continuously energized. Shortly thereafter the control relay R470 operates, the latter relay being of the slow-to-operate type. Upon operating, the control relay R470 completes, at the armature 1371 and the front contacts associated therewith, an obvious circuit, including the impulse conductor C1372, for flashing the sender lamp L1300', sixty ground impulses per minute being applied to the impulse conductor C1372. The consequent flashing of the sender lamp L1300' sixty times per minute indicates to the operator at the first operator position 1201 that sending of digits by the sender link SL-1 operatively connected to the link illustrated has been arrested for a predetermined time interval. After a predetermined further time interval the operator at the first operator position 1201 may decide to release the toll selector switch 1300, the toll line circuit 200 and the automatic switching equipment 220 in the remote exchange 20 and advise the subscriber at the calling subscriber substation A that the desired connection may not be had immediately. On the other hand, the operator at the first operator position 1201 may release the digit register and control circuit 1390 and effect reoperation thereof by again operating the sending key set DK.

Continuing now with the operation of the toll line circuit 200 to effect the delay of digit transmission from the sender link SL-1, it is further noted that, upon operating, the control relay R460 interrupts, at the contacts 466, the previously traced circuit for energizing the upper winding of the control relay R470, and completes, at the contacts 465, an alternative circuit, including the contacts 363, 437 and 512, for energizing the upper winding of the control relay R470. Also the control relay R460 completes, at the contacts 469, a holding circuit, including the contacts 363, 437, 516 and 432', for energizing the upper winding thereof. Subsequently, when the automatic switching equipment 220 in the remote exchange 20 has completed the hunting operation and is in readiness to receive the next digit, it operates to interrupt the application of ground potential to the line conductors of the toll line 201 and consequently to the simplex conductor C214 and the intermediate winding of the signal relay R210, whereby the latter relay restores. Upon restoring, the signal relay R210 interrupts, at the contacts 211, the previously mentioned path for applying ground potential to the control conductor C212 and consequently the previously traced circuit for energizing in multiple the lower windings of the control relays R460 and R470, whereby the control relay R460 is retained in its operated position due to the previously completed holding circuit for energizing the upper winding thereof and the control relay R470 operates. The control relay R470 operates due to the completion of the previously traced alternative circuit for energizing the upper winding thereof and the interruption of the previously traced circuit for energizing the lower winding thereof, the control relay R470 being of the differential type, as previously noted. Upon operating, the control relay R470 completes, at the contacts 473, a circuit, including the contacts 363, 437, 516, 469 and 456, for energizing the lower winding of the control relay R450, and prepares, at the contacts 472, a

circuit, including the contacts 453 and the impulse conductor C501, for energizing the upper winding of the control relay R450. It is noted that sixty ground impulses per minute are applied to the impulse conductor C501. At this time, in the event ground potential is present on the impulse conductor C501, both the upper and lower windings of the control relay R450 are energized, thereby to prevent operation of the latter relay, the control relay R450 being of the differential type. On the other hand, in the event ground potential does not appear upon the control conductor C501 at this time, only the lower winding of the control relay R450 is energized at this time and the latter relay operates. In any event, when ground potential is removed from the impulse conductor C501, only the lower winding of the control relay R450 is energized and the latter relay operates.

Upon operating, the control relay R450 interrupts, at the contacts 456, the previously traced circuit for energizing the lower winding thereof, and completes, at the contacts 455, an alternative circuit, including the contacts 363 and 437, for energizing the lower winding thereof. Also the control relay R450 completes, at the contacts 458, a connection, including the contacts 467 and 514, between the impulse conductor C501 and the lower winding of the control relay R510. The next time ground potential is applied to the impulse conductor C501 the above-mentioned circuit for energizing the lower winding of the control relay R510 is completed, thereby to cause the latter relay to operate. Upon operating, the control relay R510 interrupts, at the contacts 514, the previously traced circuit for energizing the lower winding thereof, and completes, at the contacts 513, an alternative circuit, including the contacts 363 and 437, for energizing the lower winding thereof. Also the control relay R510 interrupts, at the contacts 512, the previously traced alternative circuit for energizing the upper winding of the control relay R470, and completes, at the contacts 511, a further alternative circuit, including the contacts 363 and 437, for energizing the upper winding of the control relay R470. Further the control relay R510 interrupts, at the contacts 516, the previously traced holding circuit for energizing the upper winding of the control relay R460, and completes, at the contacts 515, an alternative holding circuit, including the contacts 469 and 432' and the impulse conductor C501, for energizing the upper winding of the control relay R460. When ground potential is next removed from the impulse conductor C501, the above-traced holding circuit for energizing the upper winding of the control relay R460 is interrupted, thereby to cause the latter relay to restore. Upon restoring, the control relay R460 completes, at the contacts 468, an obvious connection, including the contacts 518, between the impulse conductor C501 and the upper winding of the control relay R510. Also the control relay R460 interrupts, at the contacts 462, the previously traced path for applying battery potential by way of the resistor 401 to the control conductor C564 of the trunk 560, and completes, at the contacts 463, an obvious alternative path, including the contacts 452 and 432, for applying battery potential to the control conductor C564 of the trunk 560.

The next time ground potential is applied to the impulse conductor C501 the previously traced circuit for energizing the upper winding of the control relay R510 is completed, thereby to cause

the latter relay to restore, since both the upper and lower windings thereof are energized, the control relay R510 being of the differential type. Upon restoring, the control relay R510 interrupts, at the contacts 511, the previously traced circuit for energizing the upper winding of the control relay R470, and completes, at the contacts 512, an alternative circuit, including the contacts 466 and 477 and the grounded impulse conductor C501, for energizing the upper winding of the control relay R470. When ground potential is then removed from the control conductor C501, the above-traced circuit for energizing the upper winding of the control relay R470 is interrupted, thereby to cause the latter relay to restore. Upon restoring, the control relay R470 completes, at the contacts 471, a connection, including the contacts 454, between the upper winding of the control relay R450 and the impulse conductor C501. The next time ground potential is applied to the impulse conductor C501, the above-traced circuit for energizing the upper winding of the control relay R450 is completed, thereby to cause the latter relay to restore since both the upper and lower windings thereof are energized, the control relay R450 being of the differential type. Upon restoring, the control relay R450 interrupts, at the contacts 452, the previously traced alternative path for applying battery potential by way of the resistor 401 to the control conductor C564 of the trunk 560, and completes, at the contacts 451, the previously traced path for applying ground potential by way of the upper winding of the cutoff relay R430 to the control conductor C564 of the trunk 560. When battery potential is removed from the control conductor C564 of the trunk 560, the previously traced circuit for energizing the winding of the delay pulsing relay R1350 is interrupted, thereby to cause the latter relay to restore and effect the restoration of the control relay R1360. Upon restoring, the control relay R1360 effects the restoration of the control relay R470 in the event the latter relay is operated at this time. Also, upon restoring, the delay pulsing relay R1350 interrupts, at the contacts 1351 and the front contact associated therewith, the previously mentioned holding circuit for energizing the winding of the pulse relay R1320, and recomplete, at the armature 1351 and the back contact associated therewith, the previously traced circuit for energizing the winding of the pulse relay R1320 in the sender link SL-1 in series with the winding of the delay pulse relay R1340 in the digit register and control circuit 1390, whereupon the pulse relay R1320 is retained in its operated position and the delay pulse relay R1340 reoperates. Upon reoperating, the delay pulse relay R1340 renders the digit register and control circuit 1390 again effective to control the pulse relay R1320, whereby the next digit registered in the digit register and control circuit 1390 may be transmitted by the sender link SL-1 over the toll selector switch 1200 and the trunk 560 to the toll line circuit 200 and repeated therefrom by way of the toll line 201 to the automatic switching equipment 220 in the remote exchange 20, in the manner previously explained.

In the event the automatic switching equipment 220 in the remote exchange 20 encounters an all-trunks-busy condition prior to the reception of all of the digits registered in the digit register and control circuit 1390 in the tandem exchange 20, it operates in order to cause ground

potential to be applied intermittently to the line conductors of the toll line 201, whereby the signal relay R210 operates and restores intermittently. Upon the first operation of the signal relay R210 ground potential is applied to the control conductor C212 in order to effect operation of the control relay R460, in the manner previously described. Upon the next operation of the signal relay R210 ground potential is re-applied to the control conductor C212, thereby to complete a circuit, including the contacts 329, 332, 439 and 475, for energizing the lower winding of the cutoff relay R430, the control relay R470 having operated when ground potential was first removed from the control conductor C212, interrupting the previously traced circuit for energizing the lower winding thereof, as previously explained. Upon operating, the cutoff relay R430 completes, at the contacts 438, the previously traced holding circuit, including the contacts 363, for energizing the lower winding thereof, and interrupts, at the contacts 439, the previously traced original circuit for energizing the lower winding thereof. Also the cutoff relay R430 interrupts, at the contacts 431, the previously traced circuit for energizing the winding of the digit relay R320, thereby to retain the latter relay in its restored position, and interrupts, at the contacts 434 and 436, the previously traced circuit for energizing in series the upper and lower windings of the line relay R440 in order to cause the latter relay to restore. Further the cutoff relay R430 completes, at the contacts 431, an obvious connection, including the contacts 342 and 329, between the upper winding of the control relay R460 and the control conductor C212, whereby the control relay R460 follows the intermittent operation of the signal relay R210, in the manner previously explained. Further the cutoff relay R430 interrupts, at the contacts 437, the previously traced locking circuits for the various windings of the control relays R470, R450 and R510, thereby to insure the restoration of the latter relays. Also the cutoff relay R430 interrupts, at the contacts 432, the previously traced path for applying battery potential by way of the resistor 401 to the control conductor C564 of the trunk 560, thereby to effect the restoration of the delay pulsing relay R1350 and the control relay R1360 in the sender link SL-1. Further the cutoff relay R430 prepares, at the contacts 433 and 435, the previously mentioned circuits for respectively energizing the windings of the identity relay R420 and the rering relay R370.

When the delay pulsing relay R1350 in the sender link SL-1 restores the digit register and control circuit 1390 is rendered operative to control the sender link SL-1, whereby the remainder of the digits stored in the digit register and control circuit 1390 are transmitted by the sender link SL-1. The transmission of the digits mentioned at this time by the sender link SL-1 to the toll line circuit 200 are without effect and, after all of the digits mentioned have been transmitted, the sender link SL-1 and the digit register and control circuit 1390 are released, as previously explained. After all of the digits mentioned have been transmitted by the sender link SL-1, the cut-in relay R1260 is operated in the link finder switch 1200 in order to complete the previously mentioned operative connection between the link finder switch 1200 and the toll selector switch 1300.

At this time the signal relay R210 in the toll line circuit 200 continues to operate intermit-

tently in order to effect intermittent operation of the control relay R460. Each time the control relay R460 operates and restores it interrupts and then recompletes, at the contacts 464, the previously traced path for applying ground potential to the control conductor C564 of the trunk 560 in order to flash the front supervisory lamp L1276, in the manner previously explained. The flashing of the front supervisory lamp L1276 indicates to the operator at the first operator position 1201 that either there is an all-trunks-busy condition in the automatic switching equipment 220 in the remote exchange 20 or that the called subscriber substation therein is busy at this time. The operator at the first operator position 1201 then effects the release of the toll selector switch 1300 and advises the subscriber at the calling subscriber substation A that the desired connection may not be had immediately due to the busy condition mentioned. The operator at the first operator position 1201 then effects the release of the link finder switch 1200, in a manner more fully explained hereinafter.

After the operator at the first operator position 1201 has set up the previously traced established connection between the calling subscriber substation A in the tandem exchange 30 and the called subscriber substation in the remote exchange 20, she may perform certain controls and supervisions thereover, as explained more fully below. More particularly, the operator at the first operator position 1201 may identify the trunk group, as well as the particular trunk 560 therein, which has been seized by the toll selector switch 1300 by operating the identity key in the associated position equipment in order to cause battery potential to be applied to the line wiper 1302' of the toll selector switch 1300 and consequently to the line conductor C561 of the trunk 560. This application of battery potential to the line conductor C561 of the trunk 560 completes an obvious circuit for energizing the winding of the identity relay R420, thereby to cause the latter relay to operate and complete, at the contacts 421 and 422, obvious paths for applying ground potential to the conductors illustrated extending to the identity equipment associated with the first operator position 1201.

On the other hand, the operator at the first operator position 1201 may effect reringing over the toll line 201 by operating the ring key in the associated position equipment, whereby battery potential is applied to the line wiper 1303' of the toll selector switch 1300 and consequently to the line conductor C562 of the trunk 560. This application of battery potential to the line conductor C562 of the trunk 560 completes an obvious circuit for energizing the winding of the rering relay R370, thereby to cause the latter relay to operate shortly thereafter, the rering relay R370 being of the combination slow-to-operate and slow-to-release type. Upon operating, the rering relay R370 interrupts, at the contacts 371, the previously mentioned circuit for energizing the winding of the rering relay R410, thereby to cause the latter relay to restore shortly thereafter. Further the rering relay R370 interrupts, at the contacts 373, the previously traced path for applying battery potential by way of the resistor 310 to the control conductor C215, and completes, at the contacts 372, an alternative path, including the contacts 411, 433' and 552, for applying ground potential to the control conductor C215. When the rering relay R410 then restores it interrupts, at the contacts 75

411, the above-traced path for applying ground potential to the control conductor C215, and recompletes, at the contacts 412, the previously traced path, including the contacts 433' and 552, for applying battery potential by way of the resistor 310 to the control conductor C215. Accordingly, the operation of the rering relays R370 and R410 is effective to cause battery potential to be first removed from the control conductor C215 and then reapplied thereto a predetermined short time interval thereafter, ground potential being applied to the control conductor C215 during the time interval mentioned. This application of ground potential to the control conductor C215 during the time interval mentioned and consequently by way of the intermediate winding of the signal relay R210 and the simplex conductor C214 to the line conductors of the toll line 201 causes a rering signal to be operated in the automatic switching equipment 220 in the remote exchange 20 in the event the established connection is routed to the toll switchboard therein.

Finally the operator at the first operator position 1201 may place the trunk 560 seized by the toll selector switch 1300 in out-of-order condition by operating the out-of-order key in the associated position equipment, whereby battery potential is applied to both of the line wipers 1302' and 1303' of the toll selector switch 1300 and consequently to the line conductors C561 and C562 of the trunk 560. The application of battery potential to the line conductor C561 effects operation of the identity relay R420, in the manner previously explained. Upon operating, the identity relay R420 interrupts, at the contacts 424, the previously traced circuit for energizing the winding of the rering relay R370, thereby positively to prevent operation of the latter relay due to its slow-to-operate characteristic. Further, the identity relay R420 completes, at the contacts 423, an obvious connection between the lower winding of the order relay R520 and the line conductor C562 of the trunk 560, whereby the lower winding of the latter relay is energized in order to cause the order relay R520 to operate shortly thereafter, the latter relay being of the combination slow-to-operate and slow-to-release type. Upon operating, the order relay R520 completes, at the contacts 523, an obvious holding circuit, including the key K503, for energizing the upper winding thereof, and an obvious multiple circuit for illuminating the out-of-order lamp L502. The illumination of the out-of-order lamp L502 indicates that the toll line circuit 200 and the toll line 201 extending thereto have been placed in out-of-order condition. Also the order relay R520 interrupts, at the contacts 521, the previously traced circuit for energizing the winding of the seizure relay R360 in order to cause the latter relay to restore and effect the release of the toll line circuit 200, in a manner more fully explained hereinafter. Further, the order relay R520 completes, at the contacts 522, an obvious path, including the contacts 544, for applying ground potential to the control conductor C563 of the trunk 560, thereby to mark the trunk 560 as busy to the toll selector switches 1300 etc. having access thereto. Further, the order relay R520 completes, at the contacts 524 and 525, an obvious path for applying trouble tone potential to the windings 301 and 303 of the repeating coil 300 and consequently to the toll line 201, thereby to mark the toll line 201 in out-of-order condition to the automatic switching equipment 220.

in the remote exchange 20. After the operator at the first operator position 1201 has placed the toll line circuit 200 and the toll line 201 extending thereto in out-of-order condition she effects the release of the toll selector switch 1300. After the toll line circuit 200 has been placed in out-of-order condition it remains in such condition until the repairman has placed it again in working order; at which time the repairman operates the key K503 in order to effect the restoration of the order relay R520. Upon restoring, the order relay R520 again places the toll line circuit 200 in service, in an obvious manner.

Considering now the release of the established connection between the calling subscriber substation A in the tandem exchange 30 and the called subscriber substation in the remote exchange 20, it is noted that, in the event the subscriber at the called subscriber substation in the remote exchange 20 first initiates the release of the established connection, the automatic switching equipment 220 operates in order to cause ground potential to be removed from the line conductors of the toll line 201 in order to effect the restoration of the signal relay R210. Upon restoring, the signal relay R210 interrupts, at the contacts 211, the previously traced circuit for energizing the upper winding of the control relay R460 in order to cause the latter relay to restore. Upon restoring, the control relay R460 30 recomplices, at the contacts 464, the previously traced path for applying ground potential to the control conductor C564 of the trunk 560, thereby to complete a circuit, including the control wiper 430A of the toll selector switch 1300, the contacts 1263 and the contacts 1275 of the talk key K1280, for illuminating the front supervisory lamp L1276. The illumination of the front supervisory lamp L1276 indicates to the operator at the first operator position 1201 that the release of the established connection over the toll selector switch 1300 in the remote exchange 20 has been initiated.

At this point it is noted that, in the event the subscriber at the called subscriber substation in the remote exchange 20 desires supervision, he merely operates back and forth the associated switchhook in order to cause ground potential to be disconnected from and then reconnected to the toll line 201, whereby the signal relay R210 follows the switchhook operation mentioned, causing the control relay R460 to follow and flash the front supervisory lamp L1276, in an obvious manner.

The operator at the first operator position 1201 then reenters the connection by operating the talk key K1280 and determines whether the subscriber at the called subscriber substation in the remote exchange 20 desires supervision or has initiated the release of the established connection. Assuming that the established connection is to be released, the operator at the first operator position 1201 then effects the release of the link finder switch 1200 and the toll selector switch 1300. When the link finder switch 1200 is released the associated C. L. R. equipment and the local switch train are released, assuming that the subscriber at the calling subscriber substation A in the tandem exchange 30 has replaced the receiver of the telephone instrument thereat upon its associated switchhook at this time.

When the toll selector switch 1300 is released ground potential is removed from the control conductor C563 of the trunk 560 in order to in-

terrupt the previously traced circuit for energizing the winding of the seizure relay R360 in the toll line circuit 200, whereupon the latter relay restores in order to effect the release of the toll line circuit 200, as previously noted.

More particularly, upon restoring, the seizure relay R360 interrupts, at the contacts 362, the previously traced multiple circuits for energizing the windings of the switch relay R320 and the rering relay R410, thereby to cause the switch relay R320 to restore and to cause the rering relay R410 to restore shortly thereafter. Also the seizure relay R360 interrupts, at the contacts 363, the previously traced holding circuit for energizing the lower winding of the cut-off relay R430, thereby to cause the latter relay to restore. Upon restoring, the cutoff relay R430 reprepares, at the contacts 434 and 436, points in the previously traced circuit for energizing the winding of the line relay R440, and interrupts, at the contacts 431, the previously traced path for applying ground potential to the control conductor C564 of the trunk 560. At this time the toll line circuit 200 is completely released and available for further use.

Conclusions

From the foregoing it is apparent that a telephone system is provided, which comprises a tandem exchange including an improved automatic tandem switching network in conjunction with an automatic switchboard, whereby connections may be set up from the tandem switching network to the toll switchboard or therethrough beyond the tandem exchange independently of the toll switchboard, and the connections which have been set up may be supervised in a ready and efficient manner.

While one embodiment of the invention has been disclosed, it will be understood that various modifications may be made therein, which are within the true spirit and scope of the invention.

What is claimed is:

45. In a telephone system comprising a first exchange provided with an operator switchboard, a second exchange provided with automatic switching apparatus, a trunk extending between said exchanges, means controllable from said switchboard for extending a connection therefrom by way of said trunk to said switching apparatus, and a register sender controllable from said switchboard to register a plurality of digits and then operative to send successively a plurality of switch directing signals corresponding to the registered digits over said trunk to said switching apparatus, thereby selectively to control the operation of said switching apparatus; a trunk circuit in said first exchange associated with said trunk, said trunk circuit including a timer, means controlled by a predetermined operation of said switching apparatus for transmitting a stop send signal over said trunk, means controlled by the stop send signal transmitted over said trunk for arresting operation of said register sender and for controlling operation of said timer, and means controlled by operation of said timer for initiating reoperation of said register sender.
50. 2. In a telephone system comprising a first exchange provided with an operator switchboard, a second exchange provided with automatic switching apparatus, a trunk extending between said exchanges, means controllable from said switchboard for extending a connection there-

from by way of said trunk to said switching apparatus, and a register sender controllable from said switchboard to register a plurality of digits and then operative to send successively a plurality of switch directing signals corresponding to the registered digits over said trunk to said switching apparatus, thereby selectively to control the operation of said switching apparatus; a trunk circuit in said first exchange associated with said trunk, said trunk circuit including a timer, means controlled by a predetermined operation of said switching apparatus for transmitting a stop send signal of limited time duration over said trunk, means responsive to the application of said stop send signal to said trunk for arresting operation of said register sender, means responsive to the removal of said stop send signal from said trunk for initiating a given timing operation of said timer, and means controlled by said timer in response to the completion of said given timing operation thereof for initiating reoperation of said register sender.

3. In a telephone system comprising a first exchange provided with an operator switchboard, a second exchange provided with automatic switching apparatus, a trunk extending between said exchanges, means controllable from said switchboard for extending a connection therefrom by way of said trunk to said switching apparatus, and a register sender controllable from said switchboard to register a plurality of digits and then operative to send successively a plurality of switch directing signals corresponding to the registered digits over said trunk to said switching apparatus, thereby selectively to control the operation of said switching apparatus; a trunk circuit in said first exchange associated with said trunk, said trunk circuit including a timer, means controlled by a predetermined operation of said switching apparatus for transmitting a stop send signal over said trunk, means controlled by the stop send signal transmitted over said trunk for arresting operation of said register sender and for controlling operation of said timer, means controlled by operation of said timer for initiating reoperation of said register sender, means controlled by a busy condition encountered by said switching apparatus for transmitting a busy signal over said trunk, and means controlled by the busy signal transmitted over said trunk for returning a busy signal to said switchboard.

4. In a telephone system comprising a first exchange provided with an operator switchboard, a second exchange provided with automatic switching apparatus, a trunk extending between said exchanges, means controllable from said switchboard for extending a connection therefrom by way of said trunk to said switching apparatus, and a register sender controllable from said switchboard to register a plurality of digits and then operative to send successively a plurality of switch directing signals corresponding to the registered digits over said trunk to said switching apparatus, thereby selectively to control the operation of said switching apparatus; a trunk circuit in said first exchange associated with said trunk, said trunk circuit including a timer, means controlled by a predetermined operation of said switching apparatus for transmitting a single pulse of limited time duration over said trunk and controlled by a busy condition encountered by said switching apparatus for transmitting a plurality of rapid pulses over said trunk, means responsive to a first pulse received over said trunk for initiating operation of said timer,

means responsive to a predetermined operation of said timer for arresting further operation thereof, means responsive to a second pulse received over said trunk for arresting operation of said timer, means controlled during operation of said timer for arresting operation of said register sender, and means responsive to a plurality of pulses received over said trunk for returning a busy signal to said switchboard.

5. In a telephone system comprising a first exchange provided with an operator switchboard, a second exchange provided with automatic switching apparatus, a trunk extending between said exchanges, a repeater circuit terminating one end of said trunk in said first exchange, the other end of said trunk being associated with said switching apparatus in said second exchange, and means controllable from said switchboard for extending a connection therefrom by way of said repeater circuit and said trunk to said switching apparatus, a register sender controllable from said switchboard to register a plurality of digits and then operative to send successively a plurality of switch directing signals corresponding to the registered digits to said repeater circuit, whereby said repeater circuit repeats the switch directing signals over said trunk to said switching apparatus, thereby selectively to control the operation of said switching apparatus; said repeater circuit including a timer, means controlled by a predetermined operation of said switching apparatus for transmitting a stop send signal over said trunk, means controlled by the stop send signal transmitted over said trunk for arresting operation of said register sender and for controlling operation of said timer, and means controlled by operation of said timer for initiating reoperation of said register sender.

6. In a telephone system comprising a first operator position, a trunk circuit including a ring relay and a supervisory relay, a first trunk extending to said trunk circuit, a second trunk extending from said trunk circuit, a second operator position provided with a plurality of links, and means for setting up a connection from said first operator position by way of said trunks and said trunk circuit and one of said links to a remote point; means controllable from said first operator position for effecting operation of said ring relay during a short time interval, means responsive to operation of said ring relay for completing an operating circuit for said supervisory relay, means responsive to operation of said supervisory relay for completing a holding circuit therefor and for transmitting a no-answer signal over said first trunk to said first operator position and a recall signal over said second trunk to said second operator position, means responsive to the recall signal transmitted to said second operator position for identifying said one link included in said connection, means responsive to the reanswering of the recall on said one link at said second operator position for interrupting said holding circuit, and means responsive to restoration of said supervisory relay for arresting the transmission of the respective signals over said first and second trunks.

7. In a telephone system comprising a first operator position, a trunk circuit including a ring relay and a supervisory relay, a first trunk extending to said trunk circuit including line conductors and a control conductor, a second trunk extending from said trunk circuit including line conductors and a control conductor, a second operator position provided with a plurality of

links, and means for setting up a connection from said first operator position by way of said trunks and said trunk circuit and one of said links to a remote point; means controllable from said first operator position for effecting operation of said ring relay during a short time interval, means responsive to operation of said ring relay for completing an operating circuit for said supervisory relay, means responsive to operation of said supervisory relay for completing a holding circuit therefor including the control conductor of said second trunk and for transmitting a no-answer signal over the control conductor of said first trunk to said first operator position and a recall signal over the control conductor of said second trunk to said second operator position, means responsive to the recall signal transmitted to said second operator position for identifying said one link included in said connection, means responsive to the reanswering of the recall on said one link at said second operator position for interrupting said holding circuit, and means responsive to restoration of said supervisory relay for arresting the transmission of the respective signals over the respective control conductors of said first and second trunks.

8. In a telephone system comprising a first operator position, a trunk circuit including a ring relay and a supervisory relay, a first trunk extending to said trunk circuit including line conductors and a control conductor, a second trunk extending from said trunk circuit including line conductors and a control conductor, a second operator position provided with a plurality of links, and means for setting up a connection from said first operator position by way of said trunks and said trunk circuit and one of said links to a remote point, means controllable from said first operator position for projecting ringing current over the line conductors of said first trunk during a short time interval, means responsive to the ringing current projected over the line conductors of said first trunk for completing an operating circuit for said ring relay, means responsive to operation of said ring relay for completing an operating circuit for said supervisory relay, means responsive to operation of said supervisory relay for completing a holding circuit therefor including the control conductor of said second trunk and for transmitting a no-answer signal over the control conductor of said first trunk to said first operator position and a recall signal over the control conductor of said second trunk

to said second operator position, means responsive to the recall signal transmitted to said second operator position for identifying said one link included in said connection, means responsive to the reanswering of the recall on said one link at said second operator position for interrupting said holding circuit, and means responsive to restoration of said supervisory relay for arresting the transmission of the respective signals over the respective control conductors of said first and second trunks.

9. In a telephone system, a line selecting switch comprising mechanism having access to a plurality of lines, a line relay adapted to operate in response to seizure of the switch and also to restore and reoperate in accordance with the impulses of a digit received by the switch, means controlled by said line relay for selectively operating said mechanism to select a line accessible thereto, a device operative through a cycle to project ringing current during a predetermined time interval over a line selected by said mechanism, means for testing the idle or busy condition of a line selected by said mechanism, means controlled by said testing means in the event a line selected by said mechanism is tested as idle for operating said device through a cycle, and additional means controlled by momentary restoration of said line relay subsequent to operation of said mechanism to select a line for reoperating said device through a cycle.

10. In a telephone system, a line selecting switch comprising mechanism having access to a plurality of lines, a line relay adapted to operate in response to seizure of the switch and also to restore and reoperate in accordance with the impulses of a digit received by the switch, means controlled by said line relay for selectively operating said mechanism to select a line accessible thereto, a plurality of control relays operative through a timed cycle to project ringing current during a predetermined time interval over a line selected by said mechanism, means for testing the idle or busy condition of a line selected by said mechanism, means controlled by said testing means in the event a line selected by said mechanism is tested as idle for initiating operation of said control relays, and additional means controlled by momentary restoration of said line relay subsequent to operation of said mechanism to select a line for initiating reoperation of said control relays.
